[57] ABSTRACT

Collating apparatus having an automatic loading cycle for placing sheets of various sets in bins to organize a group of various sheets in each bin and for jogging the sheets of the group in each bin into edge alignment during the loading cycle; the apparatus having an automatic unloading cycle for stapling the group of sheets in each bin together in a book sequentially from bin to bin, unloading the book from each bin after it is stapled to a bottom conveyor below the bins, and conveying the books to a collection point. Each said collating apparatus constituting a basic machine unit of designed book making capacity to suit the needs of users in the minimal to average range. Each basic machine unit being integratable with like units in end-to-end and/or superposed relationship to suit user's needs above the minimal to average range to provide machines of larger capacity at near the same cost per book thereby obviating greatly increased costs for larger capacity machines.

SHEET #21

SHEET COLLATING MACHINE

This invention relates to automatic collating machines and in particular to a machine which receives sets of sheets and integrates and staples them into organized groups of sheets called books herein with two or more machines being positionable relative to each other in superposed and/or end-to-end working relationship to provide increased book making capacity.

An object of the invention is to provide an automatic collating machine which receives various sheets from a feeding mechanism, distributes the sheets to bins, accumulates groups of sheets in bins, jogs the sheets into edge alignment in the bins, staples the group in each bin together in a book, checks the stapler as to operating condition, unloads the books to a conveyor, and conveys the books to a stack to provide a finished product thereby reducing separate operations and handling such as unloading the bins, cross-stacking to keep proper groups, jogging, stapling, and moving and holding the groups between operations.

An object of the invention is to provide a basic unit collating machine of certain book making capacity, such as 50 books, which may be efficiently and economically engineered and manufactured on a standardized unit basis to provide an average size inexpensive machine to satisfy the demands of most users.

An object of the invention is to provide a basic unit collating machine which is usable in combination with one or more machine units to increase the book making capacity to the desired number wherein the machine units may be positioned in superposed and/or in end-to-end relationship thereby increasing capacity to the desired multiple without the necessity of engineering much larger machines at greatly increased cost per unit book to satisfy the needs of users needing different larger capacities.

An object of the invention is to provide various capacity machines at approximately the same price per book as the basic unit in full production manufacture without the premium costs involved in making different and larger size machines in low production manufacture.

An object of the invention is to provide a collating machine organized on a horizontal axis with bins inclined to the vertical and having a top conveyor for carrying the sheets to the bins and a bottom conveyor for carrying the stapled books away from the bins.

An object of the invention is to provide a top conveyor and a gate at the top of each bin which is automatically controlled to introduce sheets to each bin as desired and a bottom trap door on each bin for retaining the sheets during collating and for unloading the stapled books to the bottom conveyor to unload the bins and to convey the books to a stack respectively.

An object of the invention is to provide an automatic stepper mechanism and system which closes the gate to the bin to which a sheet has been delivered and opens the gate to the next bin for receiving the delivery of the next sheet from the top conveyor.

An object of the invention is to provide a jogging mechanism for moving the sheets in the bins into edge alignment with the jogging mechanism preferably automatically actuated each time after a sheet has been put in each bin to jog the last sheet and the previously inserted sheets into edge alignment with one another.

An object of the invention is to provide a stapler actuated by operating means which automatically sequentially staples the groups of sheets in the bins by advancing from one bin to the next bin.

5 An object of the invention is to use the advancing movement of the stapler carriage to the next bin to automatically open the bottom trap door on the bin in which the sheets have been stapled to unload the stitched book to the bottom conveyor.

10 An object of the invention is to position the jogging mechanism and the stapling mechanism on opposite sides of the machine so that the jogging mechanism may be used to abut and hold the sheets in proper sidewise position in the bins prior to the stapler moving into a bin thereby preventing displacement of the sheets by the stapler mechanism and insuring that the sheets are properly aligned when stapled.

An object of the invention is to provide means for closing all the bottom trap doors on the bins after all the groups of sheets have been stapled which is actuated automatically by the return travel of the stapler carriage to its home position after the sheets in the last bin have been stapled.

25 An object of the invention is to provide a sensor system for reading the operating condition of the stapler with the sensor interrupting further operation upon detecting that the stapler is not in operable condition.

30 An object of the invention is to provide a basic unit collating machine which may be used in multiple end-to-end relationship to increase the book making capacity as desired with the top conveyors and bottom conveyors inter-acting to deliver sheets to all the bins at the top and to receive books from all the bins at the bottom.

35 These and other objects of the invention will become apparent by reference to the following description of a collating machine embodying the invention taken in connection with the accompanying drawings, in which:

40 FIG. 1, Sheet 1, is a perspective view from the stapler side and book delivery end of a combination of two basic machine units lying end-to-end with two basic machine units in superposed position thereon and diagrammatically showing sheet feeding means in broken lines.

45 FIG. 1A, Sheet 2, is a perspective view from the jogger side and sheet inserting end of the combination shown in FIG. 1, showing the sheet feeding means in broken lines.

50 FIG. 1B, Sheet 2, is an enlarged diagrammatic showing of the feed adapter shown in FIGS. 1 and 1A.

55 FIG. 1C, Sheet 3, is an exploded perspective view of the principal structural components of a basic unit machine as shown in FIGS. 1 and 2.

60 FIG. 2, Sheet 4, is an enlarged interrupted, foreshortened, stapler side elevational view of a basic unit seen in FIGS. 1 and 1C.

65 FIG. 3, Sheet 5, is a top elevational view of a basic unit as shown in FIG. 2, Sheet 4, with portions of the top conveyor deleted to show drives.

65 FIG. 4, Sheet 8, is an enlarged partial end view of the top conveyor and gate assembly as shown at the top of FIG. 6, Sheet 6, and as on the line 4—4 of FIG. 3, Sheet 5.

70 FIG. 5, Sheet 10, is an enlarged partial top plan view of the top conveyor as seen in FIG. 4, Sheet 8.

FIG. 6, Sheet 6, is an end elevation view of the unit shown in FIG. 2, Sheet 4, as seen from the left or book delivery end, with the outboard stapling mechanism of the right side deleted, and showing the motor and drive to the top conveyor.

FIG. 7, Sheet 6, is an end elevational view of the unit as seen from the sheet receiving right end as seen in FIG. 2, Sheet 4, showing the motor and drive to the bottom conveyor and stapler on the right side.

FIG. 8, Sheet 7, is an enlarged partial side elevational view of the top portion of the bins, top conveyor, and gates as seen in FIG. 2, Sheet 4, showing internal portions in broken lines with parts broken away.

FIG. 9, Sheet 8, is an enlarged partial side elevational view of the left side of the unit (from opposite side as seen in FIG. 2, Sheet 4) showing the gate rods, radial arms, and solenoids with parts broken away.

FIG. 10, Sheet 9, is an enlarged partial side elevational view of the lower portion of the bins as seen in FIG. 2, Sheet 4, showing the bottom trap-door and over center spring latch on each bin indicating the open position of the trap-door and latch in broken lines and the closed position in solid lines with parts broken away.

FIG. 11, Sheet 9, is an enlarged detail of the spring latch as seen in FIGS. 10 and 12, Sheet 9, as seen from the right side of FIG. 12, Sheet 9.

FIG. 12, Sheet 9, is a cross-sectional view of the device shown in FIG. 10, Sheet 9, taken on the line 12—12 thereof.

FIG. 13, Sheet 10, is an enlarged face elevational view of a bin plate and an end elevational view of the jogger mechanism as seen in FIG. 6, Sheet 6.

FIG. 14, Sheet 11, is an enlarged side elevational view of the jogger mechanism taken on the line 14—14 of FIG. 13, Sheet 10.

FIG. 15, Sheet 8, is a side elevational view of a switch on the jogger mechanism taken on the line 15—15 of FIG. 14, Sheet 11.

FIG. 16, Sheet 12, is an enlarged, foreshortened, top plan view of the stapler drive transmission partly in cross-section with drive shafts shown in elevation and with the transmission exposed as seen at the bottom of FIG. 2, Sheet 4, with the carriage at the left end deleted.

FIG. 17, Sheet 13, is an enlarged cross-sectional view of the stapler carriage and transmission drive shafts shown at the bottom left end of FIG. 2, Sheet 4, showing details of the carriage and showing the drive shafts shown in FIG. 16, Sheet 12, relative to the carriage.

FIG. 18, Sheet 14, is a top plan view of the cross-slide portion of the carriage shown at the upper left of FIG. 17, Sheet 13.

FIG. 19, Sheet 15, is an enlarged cross-sectional view of the carriage and cross-slide thereon showing details of the cross-slide drive taken on the line 19—19 of FIG. 17, Sheet 13.

FIG. 20, Sheet 14, is a partial top plan view partly in cross-section of the cross-slide as taken on the line 20—20 of FIG. 19, Sheet 15.

FIG. 21, Sheet 7, is a partial side elevational view, partly in cross-section, of the cross-slide taken on the line 21—21 of FIG. 20, Sheet 14, showing the stapler attaching details of the cross-slide.

FIG. 22, Sheet 16, is a partial side elevational view, partly in cross-section, with parts broken away of the

carriage showing the linear drive details including the rails, wheels, rack, and rack engagement harmonic motion final drive means substantially as on line 22—22, FIG. 17, Sheet 13.

5 FIG. 23, Sheet 16, is a cross-sectional view of the drive details leading to the cross-slide drive as taken on the line 23—23 of FIG. 18, Sheet 14.

FIG. 24, Sheet 17, is an enlarged plan view of a stapler mounted in the stapler mounting tracks as seen in FIG. 21, Sheet 7, and FIG. 19, Sheet 15, with the stapler shown in broken lines.

FIG. 25, Sheet 17, is a side elevational view of the carriage, rails, and wheels with parts broken away taken on the line 25—25 of FIG. 17, Sheet 13.

15 FIG. 26, Sheet 18, is a diagrammatic end elevational view of the drive shafts, cams, and control switches operating the automatic unloading cycle.

FIG. 27, Sheet 18, is an enlarged side elevational view of the stapler condition sensor activating linkage as seen on the line 27—27, FIG. 16, Sheet 12.

FIG. 28, Sheet 18, is an end elevational view of the linkage seen in FIG. 27, Sheet 18, taken on the line 28—28 thereof.

25 FIG. 29, Sheet 19, is an enlarged side elevational view of one side of the sensor mechanism showing dual linkage for separately determining operating condition of two staplers showing the elements in one actuated position; the structure shown in FIG. 29, rises above the means shown in FIG. 17, Sheet 13, at the right end thereof as indicated by the line 29—29 of FIG. 17.

FIG. 30, Sheet 19, is an enlarged partial cross-sectional view of the device seen in FIG. 29, Sheet 19, taken on the line 30—30 thereof.

35 FIG. 31, Sheet 19, is an enlarged partial cross-sectional view of FIG. 29, Sheet 19, taken on the line 31—31 thereof.

FIG. 32, Sheet 19, is a cross-sectional view of FIG. 30, Sheet 19, taken on the line 32—32 thereof.

40 FIG. 33, Sheet 19, is a partial like view of the mechanism shown in FIG. 29, Sheet 19, showing the pivotal blocking movement of one of the rocker guards which is the other actuated position.

FIG. 34, Sheet 19, is a view of a portion of the elements seen in FIG. 29, showing another position of the elements.

FIGS. 35, 36, and 37, Sheet 15, are diagrammatic illustrations of stapler condition showing a jammed condition in FIGS. 35 and 36 and the operative condition in FIG. 37 in conjunction with feeler finger positions.

FIG. 38, Sheet 14, is a partial cross-sectional schematic showing of the book receiving trays, balance beams, and switches actuated by the beams and showing two superposed units.

FIG. 39, Sheet 11, is an enlarged view of the balance beam and switch seen in FIG. 38, Sheet 14.

FIG. 40, Sheets 20—21, is a schematic wiring diagram.

60 Referring now to the drawings wherein like numerals refer to like and corresponding parts throughout the several views, a collating machine basic unit 40 may be used by itself, may be used with other units 40 in end-to-end relationship; may be used with other units 40 in superposed relationship; and may be used in both end-to-end and superposed relationship with other units 40 as seen in FIGS. 1 and 1A.

For an understanding of the general organization of the basic unit 40, reference is made to FIG. 1C, Sheet 3. A bottom cross-member 41 at both ends provides support and desired elevation. A bottom frame 42 rests on the members 41. A plurality of bottom conveyor sections 43 are mounted in the bottom frame 42. A right side frame 44 and a left side frame 45 are mounted on the bottom frame 42. An end brace 46 interconnects the side frames 44 and 45 at the near end and at the far end. The near end is the book delivery end 47 and the far end is the sheet receiving end 48 as seen in FIGS. 1 and 1C. The ends are reversed in FIG. 1A. A plurality of inclined spaced plates 49 are supported between the side frames 44 and 45 and define bins 50 therebetween. A top frame 51 rests on the side frames 44 and 45 and overlies the bins 50. A plurality of gate rods 52 span the top frame 51 so as to overlie the bins 50. Each gate rod 52 has gate elements 53 fixed thereon and rollers 54 freely rotatably disposed thereon at each bin 50. A plurality of top conveyor sections 55 fit in the top frame 51 and move the sheets on the rollers 54 over the rods 52 and gate elements 53 when the elements 53 are in by-passing position. The gate rods 52 are angularly movable to swing the gate elements 53 between sheet diverting and sheet bypassing positions. A jogger mechanism 56 is attached to the left side frame 45 for jogging the sheets in the bins into edge alignment. A sheet stapling mechanism 57 is attached to the right side frame 44 for stapling accumulated sheets in the bins 50 together in a book. Each bin 50 has a bottom trap door 58. A latch 59 is mounted on the right side frame 44 at each bin trap door 58 to hold each trap door 58 open or closed as desired. The trap doors 58 upon opening drop the stapled book from the bins 50 to the bottom conveyor sections 43. The trap doors 58 when closed retain the sheets in the bins during collating. A motor 60 is mounted on the book delivery end 47 of the side frames 44 and 45 and drives the top conveyor sections 55. A motor 61 is mounted on the sheet receiving end of the side frames 44 and 45 and drives the bottom conveyor sections 43 and the stapler mechanism 57. The jogger mechanism 58 is driven by a third motor as stated in the description of the particulars of the various items which now follows.

THE UPPER CONVEYOR

More particularly, FIGS. 2, 3, 4 and 6, Sheets 4, 5, 6 and 8, the upper conveyor 70 comprises the four top sections 55. The upper conveyor 70 may be one long section but the short sections 55 are preferred. Each section 55 comprises a body 72 having a top 73, a bottom 74, and ends 75 and 76. A drive shaft 77 lies in the end 75 of each body 72 and an idler shaft 78 lies in the end 76 of each body 72. Sheaves 79 are fixed on each drive shaft 77 and free on each idler shaft 78 with their engaging surfaces lying outwardly of the body 72. The sheaves 79 are in aligned pairs. An endless tape 80 surrounds the body 72 at each aligned pair of sheaves 79. The tape is in engagement with the sheaves 79. Each upper conveyor section 55 is easily mounted on and removed from top frame 51. This facilitates clearing paper jams quickly when they occur. A pin and socket arrangement 85 is located at two corners of each section 55 and a latch is located at the other two corners which comprises a cam surface 88 on the top section 55

and a spring pressed bolt 89 on the top frame 51 engaging the cam surface 88 to hold the conveyor section tapes 80 against the rollers 54 to convey the sheets therebetween. The sections 55 may also be secured by a spring pressed bolt 68 and a cam surface 69, FIG. 4. Each drive shaft 77 has a stub 81 leading through the top frame 51. A drive pulley 71 is rotatably mounted on the top frame 51 and keyed to drive shaft stub 81. A series of belts 82 drive each drive pulley 71 on the top frame 51 leading to each top conveyor section 55. The motor 60 through a belt 83 and a belt 84 drives the belts 82, drive pulleys 71, drive shafts 77, fixed sheaves 79 and the endless tapes 80. The rollers 54 mounted on the gate rods 52 between the gate elements 53 are in alignment with the endless tapes 80. The tapes 80 bear on the rollers 54. The sheets 200 are delivered between the tapes 80 and the rollers 54, FIG. 8, Sheet 7. The tapes 80 thus convey the sheets 200 riding on the rollers 54 above the gate elements 53 and the bins 50. There may be four endless tapes 80 and four idler rollers 54 on each gate rod 52 as shown. These numbers may be varied as desired.

THE GATES

The top 64 of the gate element 53 is crowned to provide a smooth sliding surface in the event of sheet contact during sheet travel, FIGS. 2, 6 and 8, Sheets 4, 6 and 7. The conveyor section body 72 has channels 86 aligned with the gate elements 53. The channels 86 allow the upward swinging movement of the gate elements 53 above the linear line of sheet travel on the top conveyor with the gate elements inclined cam surface 66 interrupting the linear line of sheet travel. This is the gate open position.

A radial arm 62 extends from each gate rod 52, FIG. 9, Sheet 8. A plurality of solenoids 63 are mounted on the left side of the top frame 51 and one solenoid 63 is connected to one arm 62. A plurality of gate elements 53 are mounted on each gate rod 52 for angular movement therewith. The gate elements 53 may be tangs as shown which are somewhat triangular in shape and have a top crowned surface 64 normally lying in a horizontal plane terminating in a nose 65 facing the sheet receiving end 48, a bottom inclined surface constituting a sheet deflector cam 66 angling downwardly from the nose 65 toward the bin 50, and a rear side attached to the gate rod 52. The rod 52, a radial arm 62, and gate elements 53 comprise a gate 67 as referred to herein. The gate 67 is normally in closed position. The solenoid 63 is spring biased to hold the gate 67 in the normal closed position when the solenoid 63 is not energized. Sheets 200 traveling toward the delivery end 47 normally glide over the crowned surface 64 of the gate elements in the closed position of the gate 67 without touching the surface 64. Upon a solenoid 63 being energized, the gate rod 52 is moved angularly via the arm 62 swinging the gate elements 53 to raise the nose 65 above the plane of sheet travel as allowed by the channels 86 in the conveyor body 72. This locates the sheet deflector cam surface 66 in the path of sheet travel. This is the gate 67 open position. Upon the sheet engaging the raised sheet deflector cam 66 surface, it is diverted downwardly into the associated bin 50.

GATE ACTUATION STEPPER

As stated, each bin 50 has a solenoid actuated gate 67 movable from the normal closed position to an open position to load a sheet 200 into the bin 50. Each solenoid 63 is associated with an individual gate 67. An automatic stepper 90 actuates each gate 67 sequentially or as desired. In a unit 40 having fifty bins 50 there are also fifty gates 67 and fifty solenoids 63. The stepper 90 operates in conjunction with a sheet clearance reader 91.

When the stepper 90 cocks itself by application of power to its coil 324 it opens its own switch 477 S-1. This de-energizes relay CR2 and opens switch 476 CR2 which is the power supply for the stepper contacts 331 and arms 326-327, FIG. 40, Sheet 20. This also changes the positions of switches 485 and 486. When the stepper releases and the pawl moves forward, it recloses switch 477 and energizes the coil CR2 after a time delay which is caused by the resistor 479 and condenser 480 combination and this delays the energizing of CR2. This insures that the stepper has reached a new position before power is reapplied through switch 476 thereby obviating arcing in the stepper, FIG. 40, Sheet 20.

SHEET CLEARANCE READER

The reader 91, FIGS. 2 and 6, Sheets 4 and 6, comprises a lamp 92 at one end of the unit 40 which projects a beam of light lengthwise at the top of the bins 50 and a photo-electric cell 93 at the other end of the unit activated by the light beam. The bin plates 49 may be relieved or have an aperture 94 to provide a path for the light beam.

When the sheet 200 is diverted to a bin 50 its passage interrupts the light beam between the lamp 92 and the photo-cell 93. When the light beam is interrupted switch 339, P.C.-1, closes and energizes the stepper coil 324, S-1, in circuit 323 through circuit 340 and this cocks the stepper 90, FIG. 40, Sheet 20. When the stepper 90 cocks, interrupter contact 342, S-1-int., closes. This energizes the coil 337, CR-1, and contact 338, CR-1, closes and this provides a holding circuit for coil 337, CR-1, through the now closed photo-cell contact 339, PC-1. The energizing of coil 337, CR-1, also opens contact 343, CR-1, in series with stepper coil 324, S-1. This de-energizes the stepper coil 324, S-1, and from its now cocked position it makes one incremental step forward moving stepper arms 327, 328 to the next stepper contact which de-energizes the solenoid 63 at the previous gate 67 which now closes and energizes the solenoid 63 at the next gate 67 which now opens. When the sheet 200 clears the light beam, switch 339, PC-1, opens and coil 337, CR-1, is de-energized. This action proceeds sequentially from the first bin 50 through the desired number of bins until a sheet 200 is loaded in each bin 50. A unit counter 288 then may terminate automatic operation and the unit 40 then may shut down, or it may initiate the next sequence of operation of the unit, or it may condition the unit to deliver sheets to the next unit in line.

OPERATION OF DEVICE SO FAR DESCRIBED

From the foregoing description it will be understood that sheets 200 are fed to the upper conveyor 70 one at

a time. The sheets are moved by the conveyor 70 over the gates 67 and bins 50. In its "start" position the stepper 90 energizes the solenoid 63 to hold the gate 67 open at the first bin 50. Upon the first sheet coming to the first gate 67 the sheet is diverted into the first bin 50 interrupting the sheet passage reader 91 which moves the stepper to de-energize the solenoid 63 at the first bin 50 allowing the first gate 67 to close to energize the solenoid 63 on the second gate 67 to open it at the second bin 50. The second sheet on the upper conveyor 70 then is diverted into the second bin 50 where it interrupts the reader 91 light beam which causes the stepper 90 to operate and de-energize the solenoid 63 at the second bin 50 allowing the gate 67 at the second bin 50 to close and to energize the solenoid 63 at the third bin 50. The action at the third bin 50 then occurs as in the sequence described at the first two bins and the gate 67 is opened at the fourth bin to divert the fourth sheet on the conveyor into the fourth bin 50. This operation occurs sequentially and automatically at the bins until a sheet 200 has been inserted in each bin 50. The stepper 90 upon counting out then shuts down sheet feeding in the case of a single unit 40 or it transfers feeding to the next unit or units in the bank. After the sheets of one set are collated the attendant places the next set of sheets in the feeding device for delivery to the upper conveyor 70. The attendant then initiates operation which continues automatically until each bin 50 is loaded with a sheet of all the sets fed to the device.

In making a book of 60 different sheets, for example, the attendant will supervise the feeding of 60 sets of sheets to the collator which places one sheet of each set in each bin 50. The sheets are held in the bins by the trap doors 58.

BIN STRUCTURE

Each bin plate 49 has a top fin 96 which directs each sheet endwise outwardly in the bin 50 against its gravitational tendency to fall inwardly in the inclined bin 50, FIGS. 8, 10, and 13, Sheets 7, 9 and 10. After each sheet has passed the top fin 96, it is free to fall inwardly in the bin 50 and it comes to rest under the top fin 96 clear of the next sheet delivered to the bin 50. This provides that a sheet entering will avoid endwise contact with sheets in the bin and fall to the bottom trap door 58. An intermediate fin 97 is hinged on each bin plate 49 spaced below the top fin 96. The intermediate fin 97 adapts the bin 50 for receiving relatively short sheets which may not be held out of endwise contact by the top fin 96 due to the top edges of short sheets lying too far below the top fin 96. A tang 98 is mounted on each intermediate fin 97. An actuator bar 99 is connected to each tang 98. Linear movement of the bar 99 swings the intermediate fin 97 between the solid line down position of FIG. 8, Sheet 7, and the broken line up position indicated. The bar 99 is held in the desired linear position by securing means, not shown.

Each bin plate 49 has bottom deflectors 100 which guide the bottom end of sheets linearly inwardly in the bin 50 under the top fin 96 or intermediate fin 97 to locate the sheets together in a position at one side of the bin in a closely associated group to facilitate later stapling the sheets together. The bottom deflectors 100 prevent the sheets from spreading out relative to one

another at the bottom of the bin. Each bin plate 49 may also have a transverse wedge 101 at the bottom which groups the sheets close together at their edge adjacent thereto in conjunction with transverse movement of the sheets when moved by the jogging mechanism 56. A stop bar 102 along the side edge of the bins 50 prevents overtravel of the sheets in jogging and against which the sheets are jogged into alignment. Each bin plate 49 has a cut out portion 103 exposing a portion of sheets in the bins 50 for stapling, a projecting portion 104 opposite to the cut out portion 103, and a transverse slot 105 through the projecting portion 104 and through a portion of the plate 49 leading toward the cut out portion 103. The slot 105 receives and guides the bumper bar 106 of the jogging mechanism 56 which is now particularly described.

JOGGING MECHANISM

The jogging mechanism 56 comprises a shaft 110 rotatably mounted on the left side frame 45 as by brackets 111 and bearings 112, FIGS. 6, 13 and 14, Sheets 6, 10 and 11. A clutch 113 has a member 114 fixed on the shaft 110, a second member 115 free on the shaft 110 and a friction member 116 transferring drive between the fixed member 114 and the free member 115. Four drums 117 are mounted and fixed on the shaft 110. A steel tape 118 is wound on each drum 117 and has an outer end 119 projecting tangentially from the drum 117 through a guide 120. The four drums 117 are shown with a tape end 119 projecting toward the bins 50 at the bin slots 105. The jogger mechanism 56 has a bumper bar 106 lying cross-wise in all the bin slot 105. The bumper bar 106 is secured to the ends 119 of the four tapes 118. A motor 122 is mounted on the jogger mechanism 56. The motor 122 drives an automatic drive direction reversing crank 123. The reversing drive crank 123 is connected to the clutch free member 115 which drives through the friction member 116 to the fixed member 114 to drive the shaft 110 to move the shaft forwardly and reversely angularly a known angle such as about 90 degrees to rotate the drums 117 forwardly and backwardly to unwind and rewind the tapes 118 to move the ends 119 and bumper bar 106 in advancing and retracting movement relative to the side edges of the sheets in the bins 50. The degree of angular motion of the drum 117 is coordinated with the circumferential peripheral linear movement of the drum surface to advance and retract the bumper bar 106 the desired distance such as one and one half inches from its initial position. The initial position of the bumper bar 106 is manually adjusted to the width of the sheets in the bins by moving the drum 117 and clutch fixed member 114 relative to the clutch free member 115 via the friction member 116. The shaft 110 may have a hand wheel 124 with numerical designations and an index 125 to gate the setting.

The jogging mechanism 56 is automatically actuated by the circuit of the machine after the sheets of a set have been loaded into the bins 50. The motor 122 is energized by the control circuit for a period sufficient to rotate the drive device crank pin 123-A to move the shaft 110 angularly forwardly and backwardly the desired number of cycles, such as three, to move the bumper bar 106 in three quick advance and retract movements to jog the sheets 200 in the bins 50 three times.

The motor 122 drives a gear 127 through a reduction gear set in the case 128. The gear 127 drives a gear 129 keyed to the crank 123. The crank 123 is connected to the clutch free member 115 by a connecting rod 154. Reciprocation of the connecting rod 154 rocks the clutch free member 115 angularly forwardly and reversely imparting reversing drive to the shaft 110. The gear 127 has a projection 155 for opening a limit switch 126. The gearing is 1 to 3 between the gear 127 to the gear 129 so as to throw the crank 123 three full turns. Upon starting the jogger a hold relay in the circuit energizes the motor until the dog projection 155 clears the limit switch 126 and then drops out. The limit switch 126 then closes and energizes the motor 122 until the projection 155 makes a revolution and again opens the limit switch 126 and this terminates jogger cycling. The dog 155 and limit switch 126 are so adjusted that the bumper bar 106 is fully retracted relative to the bins 50 when the motor 122 stops. The three jogs directed to the sheets are integrated in the machine and the number of jogs may be established as desired. The jogger 56 is automatically actuated when all the bins receive a sheet of a set upon the last bin 50 being loaded. Thus the sheets previously in the bins 50 and the last sheet inserted in the bins 50 are automatically directly jogged into sidewise edge alignment after each set of sheets is inserted in the bins 50.

When the sheets are inserted in the bins they do not fall usually into accurate side edge alignment with each other but rather overlap and project sidewise relative to one another. This is common in sheet handling and necessitates jogging the sheets into proper side edge alignment. For this purpose the jogging mechanism 56 and sequence is provided. The jogger bumper bar 106 lies in the bins 50 in the slots 105 to contact the sheets in the bin 50 and to move them sidewise in the bin into contact with the stop bar 102 and wedge 101 thereby aligning their side edges. The sheets usually align endwise upon contact with the bin 50 trap door 58 at the bottom of each bin 50. Thus each sheet is projected by the fins 96 and/or 97 over the sheets already in the bin 50 so that it can fall downwardly in the bin 50 until it contacts the trap door 58. Upon the sheet contacting the trap door 58, it falls back toward the sheet receiving end 48 of the unit 50 under gravity due to the vertical inclination of the bins 50 and the deflectors 100 and comes to rest under the fins 96 and/or 97 and clear of the next sheet entering the bin 50. Thus the sheets fall into and come to rest in substantial endwise edge alignment. However the sidewise jogging of the sheets cause them to move endwise also under gravity so that the side-wise jogging also jogs the sheets endwise in the event that they are not in endwise edge alignment. After all the sets of sheets have been collated into the bins 50 and jogged into alignment they are ready to be stitched together in a book by the stapler mechanism 57. The means for moving the stapler mechanism 57 from bin to bin, to advance into a bin to engage the papers, to stitch the papers, retract from the bin, and move to the next bin is now described.

STAPLER TRANSMISSION

The sheet stapling mechanism 57 is mounted on a carriage 146 which is driven and operated by a transmission 132, FIG. 2, Sheet 4. Parallel spaced rails 145 extend from the transmission 132 at one end of the

machine past the bins 50 to the other end of the machine. A carriage 146 has wheels 147 rollably mounting it on the rails 145. A carriage drive shaft 134, a cross-slide drive shaft 135, and a stapler drive shaft 136 together with their respective extension shafts 134A, 135A, and 136A lie between the rails 145 and extend from the transmission 132 to the other end of the machine. The extension shafts are diametrically smaller than the drive shafts and lie within the transmission 132, FIG. 16, Sheet 12. Bearings 143 rotatably support the drive shafts at either end. A collar 139 is fixed on each extension shaft 134A, 135A and 136A. The collar 139 is a portion of clutch 137 which also comprises a normally non-driving friction drive element 140 connected to the collar 139, an electric coil 140A to activate the drive element 140 which then maintains itself clutched mechanically, and a dog 142 to de-activate the friction element 140. These clutch portions are fixed to each drive shaft and are driven portions. The driving clutch element is a hub 141 adjacent the friction drive element 140 and drive is connected between the hub 141 and friction element 140 and maintained therebetween when the friction drive element 140 is activated by the electric coil 140A and is disconnected therebetween when the dog 142 of the friction drive element contacts a pin 142A on the transmission located at a radial position to disconnect drive when its associated drive shaft is at a known angle after it has rotated a known angle in the forward direction of drive. The pin 142A at dog 142 on carriage drive shaft 134A is retractable by a solenoid to provide continuous drive in the forward direction past unused bins as later explained.

The clutch driving hub 141 on extension drive shafts 135A and 136A is connected to spur gears 266 and 267 respectively by an adapter 138. These parts are freely rotatably disposed on the extension shafts 135A and 136A for bearing support purposes. The spur gears 266 and 267 mesh with a spur gear 265. The spur gear 265 imparts drive to the spur gears 266 and 267 and their connected driving parts (I.E.) adapter 138 and hub 141 as follows.

The clutch driving hub 141 relative to drive shaft 134A is fixed on a tubular shaft 264 coaxial on the extension drive shaft 134A. Spur gear 265 is rotationally free on the coaxial tubular shaft 264 which is also free around the extension shaft 134A. A one-way clutch Y connects drive in the forward direction from the adapter 138 on tubular shaft 264 to the spur gear 265. A bevel gear 263 is fixed on tubular shaft 264. Thus in the forward drive direction the spur gear 265 rotates spur gears 266 and 267 and they are rotating and driving their associated parts I.E. adapters 138 and hubs 141. However spur gear 265 does not drive adapter 138 and hub 141 on shaft 134A as they are being driven by the bevel gear 263 and pinion gear 262 and the tubular shaft 264 on which they are mounted and connected and they drive spur gear 265.

In the reverse drive direction of bevel gear 263 and tubular shaft 264, the connected adapter 138 and hub 141 for drive shaft 134-134A are driven in reverse but spur gear 265 is not driven as the one-way clutch Y is slipping. This leaves gears 265, 266, and 267 non-driven in the reverse drive direction. However as adapter 138 and hub 141 are fixed on tubular shaft 264

as is bevel gear 263, they rotate in the reverse direction of drive to drive the carriage drive shaft 134-134A in the reverse direction via the associated clutch 137 when it is activated. In this regard the dog 142 does not de-activate the clutch 137 from shaft 134A in the reverse direction as the pin 142A is so sloped as to bypass the dog 142 in the reverse drive direction so that reverse drive continues until stopped with the carriage 146 at the home position in contact with a limit switch as later explained.

It will thus be understood that in the forward direction of drive, that drive is through pinion gear 262, bevel gear 263, tubular shaft 264, drive hub 141, adapter 138 to clutch 137 on drive shaft 134, 134A to drive same, and is from tubular shaft 264 through one-way clutch Y to spur gear 265, to spur gears 266 and 267 and then is through their respective adapters 138, hubs 141, and clutches 137 to their respective drive shafts 135, 135A, and 136, 136A.

It will thus be understood that in the reverse direction of drive that drive is through bevel gear 263, tubular shaft 264, connected adapter 138, and hub 141, and associated clutch 137 to carriage drive shaft 134-134A and that due to slippage in one-way clutch Y in the reverse direction that no reverse drive is imparted to spur gear 265 and spur gears 266 and 267 and their associated parts and they do not rotate.

It will be further understood that in the forward direction of drive that all drive shafts 134, 135, and 136 are selectively driven at times to operate associated mechanism in the carriage 146 but that in the reverse direction of drive that only carriage drive shaft 134 is driven to return the carriage 146 to the home position as the other drive shafts are not needed to perform their functions during reverse travel of the carriage 146 to the home position.

The bevel gear 263 is driven in both forward and reverse direction by a pinion gear 262, pinion shaft 260, pulley 261, the belt 131, and the motor 61. Reverse drive is effected by reversing the motor 61 as later explained.

The rotation of each drive shaft 134, 135, and 136 is transferred to gearing in the carriage 146 to carry out their functions and this is now described.

CARRIAGE

The carriage 146 has wheels 147 mounting it on the rails 145 for travel past the bins 50. The carriage 146 carries the stapler mechanism 57. Each drive shaft 134, 135, and 136 has a longitudinal peripheral key groove. Rotational movement of each drive shaft is transferred through an associated gear set in the carriage via a key 144 fixed in a gear of each gear set sliding in the key groove of each shaft as described hereinafter. A track 148 having cogs 149 is fixed parallel to the rails 145, FIG. 22, Sheet 16. A cross-head 150 is fixed on a shaft 151 and has rollers 152 engaging the track cogs 149. The shaft 151 is connected by gears 153, FIG. 17, Sheet 13, to the carriage drive shaft 134. When the carriage drive shaft 134 rotates 180°, the gears 153, shaft 151, cross-head 150, and rollers 152 make a 180° turn relative to the cogs 149 to move the carriage 146 from one bin 50 to the next bin 50 in the forward drive direction. In the reverse drive direction the carriage drive shaft rotates several revolutions to move the carriage 146 past all the bins to the home position.

STAPLER - CROSS-SLIDE ON CARRIAGE

A cross-slide 160 is slidably mounted on the carriage 146 by rods 108 and bearings 109 and carries the stapling mechanism 57 including at least one stapler 159, FIGS. 17, 18 and 23, Sheets 13, 14, and 16. The cross-slide 160 carries and advances the stapler 159 into position to stitch the accumulated sheets in the bins 50 and withdraws the stapler 159 after the stitching operation. The cross-slide drive shaft 135 drives gears 161, bevel gear 162, shaft 163, crank 164, and crank pin 165 on the carriage 146. The crank pin 165 lies in a cam slot 166 on the cross-slide 160. The drive is so coordinated that one half revolution of the cross-slide drive shaft 135 turns the crank 164 and crank pin 165 a one half turn (180°) to advance the cross-slide 160 and stapler 159 into a bin 50. After the stapler is actuated to stitch the sheets, the next one half revolution of the cross-slide drive shaft 135 turns the crank 164 and crank pin 165 a one half turn (180°) to withdraw the cross-slide 160 and the stapler 159 from the bin 50. When the stapler is advanced into the bin 50 the stapler operating mechanism 57 is actuated and this is now described.

STAPLER - MOUNTING OF STAPLER

The stapler 159 is removably mounted on the cross-slide 160 so that it may be loaded with staples or a loaded stapler substituted. The stapler 159 has a base plate 270 with extending edges, FIGS. 19, 21, and 24, Sheets 15, 7 and 17 respectively. The cross-slide 160 has a channel member 271. The base plate 270 is received in the channel member 271 with the side edges of the base plate 270 nested in the overlapping flanges of the channel member 271. The cross-slide 160 has a block 272 at one end of the channel member 271 abutting the base plate 270 and a depressible spring 273 abutting the base plate 270 at the other end of the channel member 271. A plunger 274 is housed in the cross-slide 160 and is equipped with a pin 275 engaging the spring 273. By manually depressing the plunger 274, the spring 273 is disengaged from the base plate 270 of the stapler and then the stapler 159 may be moved out of the channel member 271. In mounting the stapler 159, the user inserts the base plate 270 in the channel member 271 and slides it into the channel member 271 until the base plate 270 abuts the block 272. The spring 273 depresses as the base plate 270 passes and, upon the base plate 270 abutting the block 272, the spring 273 rises behind the base plate 270 locking the stapler 159 on the cross-slide 160. Two staplers 159 are shown with mountings therefore on the cross-slide 160 as exemplary of multiple staplers. One or more staplers 159 may be integrated in the construction of the machine as desired. Obviously one stapler 159 may be used in a unit having capacity for multiple staplers such as when short sheets are being collated.

STAPLER - CLINCHING MEANS

The stapler mechanism 57 includes the stapler 159 and the stapler clinching means 169, FIGS. 17, 18, 19, and 24, Sheets 13, 14, 15, and 17. The clinching means 169 comprises the stapler drive shaft 136, gears 171 and 172, bevel gears 173, a crankshaft 174, a crank 175, a crank pin 176, a connecting rod 177, a pin 205, a rod 206, a spring 207, a slide 208, a lower rack 178

and a first pinion gear 179, and a pinion gear telescopically splined shaft 196 in the first pinion gear 179; these are on the carriage 146 and are shown in the stapler actuated "clinched" position in solid lines with the normal unclinched position of the lower rack indicated in dotted lines at 209.

An upper rack 170 on the cross-slide 160 meshes with a second pinion gear 197 on the cross-slide 160 and which second pinion gear 197 is splined on pinion gear telescopic shaft 196. A stem 167 on the upper rack 170 has a boss 168 which overlies the stapler 159. The boss 168 and stem 167 move with the upper rack 170 to operate the stapler 159 to clinch and release. One full turn of the stapler drive shaft 136 makes a complete crank 175 rotation of 360° to operate the racks 178 and 170 to clinch and release the stapler 159 from the position of FIG. 37 through the position of FIG. 35 and back, Sheet 15, to clinch and release the stapler. The connecting rod 177 is connected to the lower rack 178 via the spring 207 and rod 206 to allow for various travels of the boss 168 to move the head of the stapler 159 various distances to compensate for various thickness of accumulated papers in the bins 50 in clinching staples. After the stapler 159 is clinched and released, its operating condition is now checked in the preferred embodiment of the machine to insure not only that the sheets are stitched together in a book in the bin but also that the stapler 159 is operable to stitch the sheets in the next bin. This checking is set forth later herein in the description of the sensor device.

In viewing FIG. 19 it should be remembered that the racks 178 and 170 are shown out of phase with one another in solid lines. Thus the dotted line showing of each rack is in phase with the solid line showing of the opposite or other rack. It is to be understood also that their associated parts are shown subject to their solid line position.

After the stapler 159 is clinched and released (and the stapler checked), the cross-slide 160 is retracted leaving the book stitched in the bin 50. The next sequence is to advance the carriage 146 to the next bin 50. This advancing movement of the carriage 146 is used to activate means to drop the stitched book from the last bin 50. The bottom trap door 58 and latch 59 mechanism is activated by the indexing travel of the carriage to the next bin and these are now described in particular.

BIN TRAP DOOR & LATCH

A hinge 180 supports the trap door 58 on an adjacent bin plate 49 at each bin 50, FIGS. 10-12, Sheet 9. The trap door 58 has means forming a cam channel 181. A cam pin 182 lies in the cam channel 181. The cam pin 182 is swung to open and close the trap door 58 by the latch 59 as follows. Each latch 59 comprises a stub shaft 183 which is pivotally mounted in the right side frame 44 at each bin 50. A cam arm 184 is fixed on the stub shaft 183 and has an outer end supporting the cam pin 182 for swinging the cam pin 182 in the cam channel 181 to open and close the trap door 58. A boss 185 is fixed on the stub shaft 183 and a lever clevis 186 is mounted on the boss 185. A spring anchor 187 is fixed on the right side frame 44 above the axial center of the stub shaft 183. A spring 188 is connected at one end to the anchor 187 and at the other end to the boss 185 at

the clevis 186 which is off center on either side of the stub shaft 183 in its open or closed position relative to the spring anchor 187 and line of tension of the spring 188. The spring 188 thus holds the trap door 58 in either the open or closed position depending on the off center position of the clevis 186 which controls the angular position of the stub shaft 183, cam arm 184, and cam pin 182 in the cam channel 181 of the trap door 58. The clevises 186 on adjacent bins are alternately staggered from bin to bin to avoid interference with one another. A dog 189 on the carriage 146 is adapted to contact each clevis 186, FIG. 22, Sheet 16, during forward incremental movement of the carriage 146 from bin to bin to swing the clevis 186 to the trap door 58 open position thereby unloading the stitched book from the previous bin 50 as the carriage moves to the next bin 50. After all the books are stitched and unloaded from all the bins 50, the carriage 146 is returned to its start position and this return movement moves the dog 189 relative to all the clevises 186 on all the bins to operate the latch 59 to close all the trap doors 58 on all the bins 50. As the books drop out of the bins they are received by the bottom conveyor and this is now particularly described.

BOTTOM CONVEYOR

The bottom conveyor 190 comprises the sections 43 which are mounted on the bottom frame 42, FIGS. 1-C and 2, Sheets 3 and 4. Each bottom conveyor section 43 is substantially the same as the top conveyor section 55 having endless tapes 80 or a wide belt and a driven shaft having a projecting stub 81 driven by a pulley 71 mounted on the bottom frame 42 and belts 191, 131, and 130 from the motor 61 and belts 194 leading between the pulley 71, 192, and 193 on the bottom frame to transfer drive to the conveyor sections 43 downstream from the motor belts. The bottom conveyor 190 receives the books as they slide down from the bins and conveys them to the book delivery end of the unit 40. When the units 40 are superposed on one another, as shown in FIG. 1, the bottom conveyor 190 of a superposed unit 40 may be deleted if desired and the top conveyor 70 on the unit 40 below the superposed unit 40 of used as the bottom conveyor of the superposed unit 40 wherein the circuit reverses the travel direction of the tapes 80 to move the books to the book delivery end of the unit.

SHEET FEEDING AND BOOK UNLOADING

A sheet feeder 199 feeds the sheets 200 directly to the upper conveyor 70, FIG. 1-A, Sheet 2, of a single unit 40 and to units when end-to-end. With superposed units a feed adapter 291 is located between the feeder 199 and the units 40 to feed sheets to the upper and lower units 40. The gates 67 load the bins 50 with the sheets 200. The sheets 200 are aligned by the jogger mechanism 56. The stapler mechanism stitches the sheets 200 in each bin into a book 201. The trap doors 58 open to unload the books from the bins 50 to the lower conveyor. The lower conveyor 190 moves the books 201 out of the unit 40. A hopper basket 202, FIG. 1, receives the books from the lower conveyor 190. With the units 40 positioned end-to-end, the upper conveyors 70 on each unit 40 transfer sheets 200 to one another and the lower conveyors 190 on each

unit 40 transfer the books 201 to one another. The operations of the foregoing resume occur automatically as actuated and controlled by the circuits of the unit 40 which are later described.

- 5 The hopper baskets 202 rest on legs 370, 371 which are pivotally mounted at 372 on the book delivery end 47 of the side frames 44 and 45, FIGS. 1, 39, and 38, Sheets 1, 11, and 14 respectively. The legs 370, 371 constitute a lever balance beam. The basket 202 rests on the legs 370, 371 on one side of the pivot 372 and a bracket 373 overlies the leg 371 portion 374 on the other side of the pivot 372. A spring 375 lies between the portion 374 and the bracket 373 urging them apart to resiliently support the basket 202 on the leg 370. A limit bolt 376 is welded to the portion 374 and extends freely through an aperture 377 in the bracket 373. A nut 378 is turned on the bolt 376. The bolt 376 and nut 378 limit the upward pivotal motion of the leg 371 when the basket is removed, empty, or lightly loaded. A stop 379 is welded on the leg 371 and faces the bracket 373. The stop 379 limits the downward pivoting of the leg 371 when the basket is sufficiently loaded to compress the spring 375. The resistance of the spring 375 is pre-calculated and adjusted to support a desired basket load such as 30 pounds so that a load of thirty pounds or more compresses the spring 375 and abuts the stop 379 against the bracket 373. In so compressing the spring 375, the leg portion 374 swings upwardly. A 20 plunger 380 is fixed on the leg portion 374. A normally closed basket switch 474 in circuit 417 is actuated by the plunger 380 to open when the leg portion 374 swings upwardly. The basket switch 474 is in the unit 40 unloading circuit. When the load limit switch 474 opens, the unloading operation of the unit 40 shuts down. Thus the unit 40 when stitching the sheets 200 into books 201 and delivering the books 201 to the baskets 202 is prevented from overloading the baskets 202 with too heavy a load for easy handling. The shut down of the machine advises the operator to remove the loaded baskets 202 and to place an empty basket 202 on the legs 371. Upon doing so the plunger 380 is withdrawn from the load limit switch 474 which then closes and the unit 40 resumes operation. The leg 370 is similarly equipped and acts in the same way as the leg 371. It will be noted that the portion 374 of leg 370 lies at an angle to the leg 370 while the portion 374 of the leg 371 does not. It will thus be understood that the 25 basket support legs 370, 371 may be modified and equipped in various ways and that the means shown and described are exemplary.

STAPLER OPERATING CONDITION CHECKER

- 55 After the stapler 159 has been actuated to stitch, the cross-slide 160 lies in the advanced position, and before the cross-slide 160 is retracted at each bin 50, the operating condition of the stapler 159 or staplers is checked by a sensor device 210 which leaves a check switch open interrupting the circuit controlling the retraction of the cross-slide if the stapler is not in proper operating condition and which closes a check switch so as not to interrupt the circuit controlling retraction of the cross-slide if the stapler is in proper operating condition.

In this regard the stapler may not be in proper operating condition in two instances — one with the

stapler head and anvil jammed together in the clinched position — the other with the stapler head and anvil separated but the staple clip jammed in the stapler head. The proper operating position of the stapler is with the anvil and stapler head separated with the staple clip in the "out" position relative to the stapler head so as to be ready to strike. These three positions of the stapler are read by the sensor device 210 to either close the check switch or leave the check switch open. Thus when the stapler is jammed, the sensor interrupts the automatic sequence of the machine and leaves the cross-slide advanced in the bin 50 where the stapler became jammed. This leaves the papers in the bin 50 for inspection to insure proper stitching, prevents unloading a loose group of papers on the bottom conveyor if not stitched together, prevents the jammed stapler from dragging the papers from the bin, shuts down the automatic sequencing of the machine, and advises the operator of stapler malfunction and gives the operator time and opportunity to repair the stapler to proper operating condition.

STAPLER CHECKER STRUCTURE

The sensor device 210, FIGS. 16 and 19, and FIGS. 27 to 34, Sheets 12, 15, 18 and 19 respectively, comprises a square linear shaft 211 which lies parallel to the rails 145 so that the carriage travels axially of the linear shaft 211. Of course round shafts with keys may be used in all instances where square shafts are described. The linear shaft 211 has an end freely bearinged at the book delivery end of the machine and an end freely bearinged in the transmission 132. A lever 212 is keyed on the linear shaft 211 and lies within the transmission 132, FIGS. 27-28, Sheet 18. A knee link 213 is pivoted on a tab 214. Paired legs 215 and 216 are spaced at their top ends and pivoted at their bottom ends. The legs 215 and 216 at their bottom ends are pivoted on the knee link 213. Each leg 215-216 has a spring retainer cup 217 and 218 respectively at its top end. One leg 215-216 at its bottom end has a stop 219 abutting the other leg 215-216 limiting outward pivotal movement of the legs 215, 216 relative to one another. A spreader spring 220 lies between the cups 217, 218 spreading the legs 215-216 at their tops relative to one another as limited by the stop 219. The legs 215-216 may pivot toward one another by compression of the spring 220. One leg 215 is pivotally connected to the lever 212 on the linear shaft 211. A position spring 221 lying between the legs 215-216 and the frame member 222 holds the legs 215, 216 against the frame member 222 in their non-checking normal position which is indicated in FIG. 27 by the broken line showing. The legs 215, 216 through the lever 212 angularly locate the linear shaft 211 in its normal angular position. A sensor switch cam 223 is fixed on the linear shaft 211, FIG. 26 (left end) within the transmission 132. A sensor switch 224 lies adjacent the sensor cam 223, FIG. 26, Sheet 18. The switch 224 lies in the cross-slide retract circuit so that this circuit is dependent on switch 224 being closed before this circuit can be activated by another switch. With the legs 215, 216 held against the frame member 222 by the position spring 221, the lever 212 angularly positions the linear shaft 211 to angularly position the sensor cam 223 out of contact with the sensor switch 224 leaving it open which is the normal position of the parts.

In clinching the stapler, the stapler drive shaft 136 makes a full rotation, FIG. 27. A sensor actuator cam 225 is fixed on the stapler drive shaft 136 and a coacting cam roller 226 is carried by the leg 216, FIG. 27. 5 The actuator cam 225 first contacts the cam roller 226 on the leg 216 as shown in the dotted line position. When the stapler drive shaft 136 rotates, the cam 225 moves the legs 215, 216 to the solid line position seen in FIG. 27, Sheet 18, from the indicated dotted line position; this moves the linear shaft 211 angularly to move its switch cam 223 to close the sensor cam switch 224 by moving the sensor cam 223 angularly into contact with the switch 224. This occurs when the linear shaft 211 is able to move angularly in its full angular motion without being blocked by a stapler being in a non-operative condition as hereinafter explained. This angular movement of the linear shaft 211 also actuates the sensor elements which check the operating condition of the stapler now described and both block full angular movement of the linear shaft 211 or allow it to move fully as stated.

A plate 230 is mounted on the carriage 146 adjacent the linear shaft 211, FIGS. 29 to 34, Sheet 19. A bearing 231 is axially slidably disposed on the shaft 211. The plate 230 and bearing 231 are connected together for axial travel along the shaft 211 with the carriage 146. The bearing 231 is rotatable relative to the plate 230 and carriage 146. The bearing 231 is radially keyed to the shaft 211 for angular movement with the shaft 211 and to move with the shaft 211 angularly at all points axially along the shaft 211. A key tab 232 is fixed on the bearing 231 for both axial and angular movement therewith. A rocker guard 233 is pivoted on the plate 230 at the pivot 234. The rocker guard 233 has a central notch 235 and a raised surface 236 on both sides of the notch 235. The key tab 232 is adapted to either lie in the notch 235 or abut the raised surface 236 of the rocker guard 233. The angular position of 30 the rocker guard 233 relative to the key tab 232 is controlled by mechanism hereinafter explained. The key tab 232 is moved angularly toward and away from the rocker guard 233 by angular movement of the shaft 211 as previously explained.

45 The rocker guard 233 has a wing 237 pivotally connected to a block 238 which is moved up and down by the feeler finger linkage later described. When the block 238 is intermediately positioned as seen in FIG. 29, the rocker guard 233 is centrally positioned with its notch 235 in alignment with the key tab 232. When the block 238 lies on either side of its intermediate position, FIGS. 33 and 34, the raised surface 236 of the rocker guard 233 is aligned with the key tab 232 and it cannot enter the notch 235 and thus cannot move angularly as far as it could if the notch 235 were in alignment to receive the key tab 232. This difference in angular movement of the shaft 211 makes the different of whether the cam 223 is moved to close or to open the switch 224, FIG. 26, Sheet 18.

60 Operationally the sensor items so far described have the following conditions. (a) If the linear shaft 211 is rocked angularly and the rocker guard is so positioned that a high surface 236 on either side of the notch 235 engages the key tab 232, FIG. 33, the linear shaft 211 cannot move angularly the required angle to locate the sensor cam 223 to close the switch 224 thus leaving it open in the circuit which prevents retraction of the

cross-slide. This condition occurs when the rocker guard 233 is so positioned by the stapler when it is not in proper operating condition. (b) If when the linear shaft 211 is rocked angularly and the rocker guard is so positioned that the low notch 235 engages the key tab 232, FIG. 29, the linear shaft can move as required angularly to locate the sensor cam 223 closing the switch 224 to complete the circuit to allow the cross-slide to be retracted. This condition occurs with the rocker guard 233 so positioned when the stapler is in proper operating condition.

The feeler finger linkage is now described. The block 238 is fixed on a push-pull rod 240 by adjusting nuts 241. The rod 240 has an upper end pivotally connected to an arm 242. The arm 242 is pivotally supported by a bearing 243 in turn supported by the plate 230. The arm 242 has a keyed aperture such as the square hole 244. A square cross shaft 245 is axially slidably positioned in the square hole 244 of the arm 242. The square cross shaft 245 and arm 242 are thus keyed for angular movement together with the square cross shaft 245 being axially movable relative to the arm 242 and plate 230. This allows the shaft 245 and the end 246 of the square cross shaft 245 remote from the arm 242 to travel with the cross-slide 160 and the stapler fixed to the cross-slide into a bin 50, FIG. 19, Sheet 15. The remote end 246 of the square shaft is supported by a bearing 247 on the cross-slide. A radial feeler finger 248 is fixed to the remote end 246 of the square cross shaft 245. The feeler finger 248 has a low point 249 and a high point 250 for contacting the stapler 159. The stapler 159 has a head 251, a staple clip 252 in the head 251, and an anvil 253 below the head 251 and the staple clip 252. When the stapler is at rest in proper operating condition, the head 251 and clip 252 are spaced from the anvil 253 and the clip 252 extends from the head 251 so that upon activation and contact with the anvil 253 it may move into the head 251 as the staple is being moved out into the book and clinched, FIG. 35, Sheet 15. After clinching the staple, the head 251 should (1) retract from the anvil and (2) the staple clip should extend from the head as shown in FIG. 37. If either of these actions do not occur the stapler 159 is not in proper operating condition to stitch the next group of sheets. Thus the stapler 159 may not be in proper operating condition (1) with the head 251 and staple clip 252 jammed against the anvil 253 as shown in FIG. 35, and (2) with the head 251 retracted from the anvil 253 but with the staple clip 252 jammed in the head 251 as shown in FIG. 36.

The feeler finger 248 is moved in to check the stapler 159 by a radial arm 254, FIG. 29, on the linear shaft 211, a link 255 having opposite ends with one end pivoted on the end of the radial arm 254 and the other sliding on the push-pull rod 240 with a spring 239 transferring link 255 movement to the push-pull rod 240 in the "up" or "drive" direction to pivot the cross shaft 245 to move the feeler finger 248 in an arc toward the stapler 159. The spring 256 allows for full angular movement of the linear shaft 211, radial arm 254, and link 255 regardless of the travel of the feeler finger 248 and push rod 240 relative to the stapler 159.

Thus when the stapler drive shaft 136 rotates the cam 225 against the legs 215 and 216, FIG. 27, they move the lever 212 and linear shaft 211 angularly to

swing the arm 254 and link 255 to move the push rod 240 upwardly, FIG. 29, to swing the arm 242 and cross shaft 245 angularly to swing the feeler finger toward the stapler 159 while at the same time the key tab 232 is also swung up toward the rocker guard 233. Due to the designed linkage, the arm 254 actuates the feeler finger 248 to assume its position relative to the stapler 159 prior to the key tab 232 swinging into engagement with the rocker guard 233. The spring 239 between the link 255 and the push rod 240 allows for travel difference between the push rod 240 and the arm 254 and insures that the feeler finger 248 has taken its position before the key tab 232 engages the rocker guard 233. Since the position of the rocker guard 233 is controlled by the position of the push rod 240 which in turn is positioned by the position of the feeler finger 248, the rocker guard 233 is swung to its position as controlled by the feeler finger before the key tab 232 comes into contact with it. If the high surface 236 is located in front of the key tab 232, it blocks further angular motion of the linear shaft 211 and the spring 220 between the legs 215-216 compresses as the cam 225 continues to move against the legs 215, 216, FIG. 27, Sheet 18. If the notch 235 is located in front of the key tab 232, it allows more angular movement of the linear shaft 211.

When the stapler 159 is in proper operating condition, FIG. 37, the low point 249 of the feeler finger 248 contacts the staple clip 252 to angularly position the feeler finger 248, cross shaft 245, and arm 242, FIG. 29, Sheet 17, to axially locate the push-pull rod 240 and block 238 to pivot the rocker guard 233 with its notch 235 aligned with the key tab 232 on the linear shaft 211 so that the key tab may enter the notch 235 so that the linear shaft 211 may make its additional angular motion to position the switch cam 223 to close the switch 224 so that the cross-slide 160 return circuit is closed through the switch 224 and thus the cross-slide 160 may be retracted when the cross-slide retract switch 283 is closed to continue automatic cycling. Conversely, when the stapler 159 is jammed (A) with the head 251 and clip 252 against the anvil 253, FIG. 35, Sheet 15, the feeler finger high point 250 contacts the head 251 to angularly position the feeler finger 248, cross shaft 245 and arm 242, FIG. 34, Sheet 19, to axially locate the push-pull rod 240 and block 238 to pivot the rocker guard 233 with its notch 235 out of alignment with the key tab 232 and with its high surface 236 in alignment with the key tab 232 and the key tab 232 abuts the high surface 236, FIG. 33, and the linear shaft 211 may not make its full angular motion and the check switch 224 is left open interrupting the cross-slide circuit and the cross-slide 160 cannot be retracted by closing the cross-slide return switch so that automatic cycling is interrupted and the machine shut down.

When the stapler 159 is jammed (B) with the head 251 retracted from the anvil 253 but with the clip 252 jammed in the head, FIG. 36, Sheet 15, both the high point 250 and low point 249 of the feeler finger fall out of contact with the stapler 159 below the head 251 and clip 252 to angularly position the feeler finger 248, cross shaft 245 and arm 242 to axially locate the push-pull rod 240 and block 238 to pivot the rocker guard 233 with its notch 235 out of alignment with the key tab 232 and with its high surface 236 in alignment with the key tab 232 so that the key tab 232 abuts the high

surface 236, FIG. 33, and the linear shaft 211 may not make its full angular motion and the check switch 244 is left open interrupting the cross-slide circuit and the cross-slide 160 cannot be retracted by closing the cross-slide return switch so that automatic cycling is interrupted and the machine shut down.

STAPLING AND BIN UNLOADING SELF- REPEATING CYCLING

The drive shafts 134, 135, and 136, FIG. 26, Sheet 18, each have a cam 134C, 135C, and 136C respectively in the transmission 132. The cam 134C has two diametrical lobes and the cams 135C and 136C each have one radial lobe. The cams open and close switches in the automatic circuit controlling sequences in an operation cycle of advancing the cross-slide 160 toward the bin, actuating the stapler 159, checking the operational condition of the stapler, retracting the cross-slide 160 from the bin, and indexing the carriage to the next bin with the next cycle occurring automatically as follows.

The cross-slide drive shaft 135 makes a one-half rotation to advance the cross-slide and a one-half rotation to retract the cross-slide and its cam 135C thus has two stationary positions 180° apart corresponding to the advanced and retracted positions of the cross-slide. A "stapler clinch" switch 280 and a "carriage index" switch 281 lie adjacent the cam 135C. The switches 280 and 281 are 180° apart corresponding to the two positions of the cam 135C and one switch 280 or 281 is closed by the cam 135C at one time depending on the cam 135C position at the switch 280 or 281.

The carriage index drive shaft 134 makes a one-half rotation to index the carriage to the next bin and its cam 134C has two stationary positions and thus has two lobes to actuate a single switch upon a one-half turn. A cross-slide "advance" switch 282 lies adjacent the cam 134C actuating position so that one lobe of the two lobe cam 134C closes the switch 282 when the carriage drive shaft 134 lies stationary in either of its stationary 180° positions.

The staple clinch drive shaft 136 makes a full rotation to clinch and release the stapler 159 and its cam 136C has a single lobe corresponding to its one stationary position. A cross-slide "retract" switch 283 lies adjacent the cam 136C stationary position so that its lobe closes the switch 283 when the stapler drive shaft 136 lies stationary. The stapler "operating condition" switch 224 is in series with the switch 283 so that both must be closed to complete a circuit.

It will be remembered that the clutches 137 on each drive shaft 134, 135, and 136 are electrically actuated and mechanically de-actuated to transfer and disconnect drive and that the clutches 137 mechanically maintain clutch drive until mechanically de-actuated by contact with its associated pin 142 whereupon drive is disconnected from the associated drive shaft. Thus the clutches 137 on the drive shafts 134, 135, and 136 are actuated by a switch and, upon occurrence of desired angular movement of the shaft, each clutch is mechanically de-clutched or de-activated by the pin 142 which disconnects drive to its shaft. The pins 142 thus stop the drive shafts after they have performed their function with their cams 134C, 135C, and 136C positioned relative to the switches 280-283 such as shown in FIG. 26.

The switch 280, 281, 282 and 283 adjacent each cam 134C, 135C, and 136C are actuated to initiate the next sequence in the cycle by the position of its associated drive shaft 134, 135, and 136 advancing the cam thereon relative to the switch. Thus the self-repeating cycling is effected by the switch for the next operational sequence being closed by the drive shaft for the last operational sequence after the last operational sequence is completed.

Thus the cross-slide 160 "advance" switch 282 closes the circuit to the clutch 137 on the cross-slide drive shaft 135 but rotation of shaft 135 is actuated by the cam 134C on the carriage index drive shaft 134. The stapler clinch switch 280 closes the circuit to the clutch 137 on the stapler clinch drive shaft 136 but rotation of shaft 136 is actuated by the cam 135C on the cross-slide drive shaft 135.

The cross-slide 160 retract switch 283 closes the circuit to the clutch 137 on the cross-slide drive shaft 135 but rotation of shaft 135 is actuated by the cam 136C on the stapler clinch drive shaft 136.

The carriage index switch 281 closes the circuit to the clutch 137 on the carriage index drive shaft 134 but rotation of shaft 134 is actuated by the cam 135C on the cross-slide drive shaft 135.

Upon closing a start switch 420, 445 in the master control circuit in parallel with switch 282 and closing rest button switch 470 and the self repeating cycling is initiated and continues automatically as follows:

The start switch closes a circuit to activate the clutch 137 on the cross-slide drive shaft 135 which transfers drive to shaft 135 and the cross-slide is advanced into the bin with rotation of the shaft 135 bringing the cam 135C into closing contact with switch 280.

Switch 280 closes a circuit to activate the clutch 137 on the stapler drive shaft 136 which transfers drive thereto and the stapler is clinched and released with rotation of the shaft 136 bringing the cam 136C into closing contact with the switch 283 and makes a circuit if the check switch 224 in series is closed.

As previously set forth the stapler operating condition check switch 224 is in series with the cross-slide retract switch 283 so that the check switch 224 must be closed or the circuit from the switch 283 will be open preventing a circuit to the clutch 137 on the cross-slide drive shaft 135 and cycling shuts down. In this regard, the cam 225 on the stapler clinch drive shaft 136 actuating the stapler operating condition sensor mechanism is so angularly positioned as to operate the sensor mechanism to establish the position of the check switch 224 in either a closed or open condition prior to the cam 136C closing the switch 283 to retract the cross-slide.

Switch 283 closes (and if check switch 224 is closed) and closes a circuit to activate the clutch 137 on the cross-slide drive shaft 135 which transfers drive thereto and the cross-slide is retracted from the bin with rotation of the shaft 135 bringing the cam 135C into closing contact with switch 281.

Switch 281 closes activating a circuit to the clutch 137 on the carriage index drive shaft 134 which transfers drive to the shaft 134 and the carriage is indexed to the next bin unloading the stitched book as stated with rotation of the shaft 134 bringing the cam 134C into closing contact with switch 282.

Switch 282 closes to activate a circuit to the clutch 137 on the cross-slide drive shaft 135 which transfers drive to the shaft 135 and the cross-slide is advanced into the bin 50 and the rotation of the shaft 135 brings the cam 135C into closing contact with switch 280.

The cycle now automatically self repeats itself with the pins 142 declutching the clutches 137 at the desired angular position of its associated drive shaft and it will be understood that the switches 280-283 close only momentarily to activate their associated clutch 137 and then open.

A limit switch 421, 446 adjacent the last bin upon being contacted by the carriage in its indexing movement past the last bin interrupts the automatic cycling. The operator actuates the return traverse button to reversely drive the carriage index drive shaft 134 to move the carriage back to its home position at the last bin where a second limit switch 430, 454 is contacted by the carriage shutting down the return traverse.

SHEET FEEDING AND FEED ADAPTER

The sheet printer and/or sheet feeder 199, FIG. 1-A and 1-B is equipped with an automatic circuit and a sheet counter 198 which counts each sheet as it is printed and/or delivered to the unit or units 40. The counter 198, upon counting out the desired pre-set number of sheets, shuts down the operation of the feeder 199 and this terminates delivery of sheets from the feeder 199 to the collator. The feeder counter 198 is pre-set to print any number of sheets equal to or less than the sheet capacity of the collator equipment to which it feeds the printed sheets.

When a bank of in-line units 40 is used, their top conveyors, are also inline and the top conveyor on the first unit 40 delivers sheets to the top conveyor of the second unit 40 in line after the bins 50 of the first unit 40 are each loaded with a sheet of the set. Thus in the in-line arrangement, the feeder 199 delivers sheets directly to the top conveyor of the first unit 40 which transfers the sheets 200 to the top conveyor of the second unit 40 in-line.

A switch 311-A is in parallel with a switch 311 in lead 310, FIG. 40, to run the upper conveyor motor on the first unit 40 to deliver sheets to the top conveyor of the second in-line unit after the first unit in-line is loaded with sheets.

However, when a bank of superposed units 40 is employed the top conveyors of the upper and lower units 40 are not in line and a feed adapter 291 is positioned between the feeder 199 and the collator bank to control sheet feeding such as first to the top conveyor of the lower unit or units and then to the top conveyor of the upper units or units, FIG. 1-B, Sheet 2. The feed adapter 291 has a lower track 292 to the top conveyor of the lower units, an upper track 293 to the top conveyor of the upper units, and a receiving track 294 taking sheets from the feeder 199. A switch gate 295 is located in the receiving track 294 and normally delivers sheets via the lower track 292 to the lower unit or units. Upon the bins of the lower units being loaded, the switch gate 295 is thrown to deliver sheets via the upper track 293 to the upper unit or units. A counter 299 on the feed adapter 291 controls the position of the switch gate 295 in the feed adapter 291. The switch gate 295 is operated by a solenoid 308 which is ener-

gized to throw the switch gate to the upper track 293 upon the counter 299 counting out when the proper number of sheets have been delivered to the lower unit 40. The feed adapter 291 may be driven independantly 5 or by the motor 61 and suitable drive connections.

Assuming that a bank of four units 40 is used, with each unit having a 50 sheet capacity, with two units in-line below and two units superposed above, the bottom units have a combined capacity of 100 sheets and the

10 upper units have a combined capacity of 100 sheets, FIG. 1. All four units have a two hundred sheet total capacity but are adapted to handle less than the full capacity as explained later. The operation of a single

15 unit has been described and is further described in the explanation of the operation of a bank of four units and the control circuits and equipment in relation to the wiring diagram.

FEED ADAPTER CIRCUITS

20 Referring now to the wiring diagram, FIG. 40, Sheets 20-21, main power lines 300 and 301 carry 115 volt alternating current or other basic voltage and current. The feed adapter counter 299 has a clutch coil 302 in lead 298 and a count coil 303 in lead 305 between lines 300, 301. Switches 296 and 297 in lead 298 are closed connecting in the counter 299 when CR3 is energized as stated hereinafter. A sheet count switch 304 in the feeder adapter 291 receiving track 294, FIG. 1-B, Sheet 2, is actuated to close by the passage of a sheet. The count coil 303 and sheet count switch 304 are in series in the lead 305. Upon a sheet passing the count switch 304, the count coil 303 receives an impulse and actuates the counter 299 to count one increment. Upon 35 the feed adapter counter 299 counting out the number pre-set thereon, it actuates a switch 306 in a lead 307 between the lines 300-301 which includes in series a solenoid coil 308 of the feed switch gate 295 of the feed adapter 291. Upon the switch 306 closing, the coil 308 40 is energized and the feed switch gate 295 thrown to feed the sheets to the top conveyor of the upper superposed units of the bank.

The feed adapter 291, counter 299, and circuits are used only with superposed units. Their sole function is 45 to determine the point at which the feed of sheets is to be changed to the superposed units and to throw the switch gate 295 in the feed adapter 291 to the top conveyor of superposed units at the proper count.

BASIC UNIT CIRCUIT - BIN LOADING

The electrical equipment, circuitry and operation of a unit 40 is now described. The photo-electric reader amplifier 91 in lead 309 between the lines 300, 301, has a photo-cell 93 and a lamp 92 directing a light beam to the cell 93 scanning the bins 50 below the gate 67 and is constantly energized to detect the passage of a sheet 200 through a gate 67 into a bin 50 which interrupts the beam. The upper conveyor motor 60 is in a lead 310 between the lines 300, 301. A switch 311 (CR-3) in lead 310 controls the circuit of the motor 60; the switch 311 is closed and maintained closed by the system during sheet loading in the first unit 40.

A transformer 312 lies in a lead 313 between the lines 300, 301. A rectifier 314 is connected to the transformer 312. Lines 320 and 321 from the rectifier 314 supply low voltage direct current to the following system.

A start switch 322 lies in a lead 323 between the lines 320, 321. The coil 324 of the stepper 90 also lies in the lead 323 in series with the start switch 322. Upon the start switch 322 being closed it energizes the coil 324 causing its associated armature to move. The armature movement is transferred to the stepper 90 sections 325 and 326 to move their sweep contact arms 327, 328 one increment (I.E.) initially from the home contact H to contact I of stepper section 325 and subsequently from numbered contact to the next numbered contact sequentially each time the coil 324 is energized as set forth later herein.

A lead 329 from line 321 is connected to the home contacts H and to the sweep arms 327 and 328. A lead 330 from the line 320 is connected to the contacts 1-50 of the sections 325 and 326 via an individual lead 331 to each numbered contact point 1-50 on the sections 325, 326. Only a few leads 331 are shown. A bin gate 67 solenoid 63 coil 332 is disposed in each individual lead 331. Upon the sweep arms 327-328 of sections 325-326 moving to a numbered contact the associated bin gate solenoid coil 332 is energized and the associated gate 67 in the top conveyor is opened to the associated bin 50. In the first instance the sweep arm 327 of section 325 moves to contact 1 and the solenoid coil 332 is energized and the first gate 67 is opened to divert a sheet into the first bin 50 from the upper conveyor 70.

With the sections 325-326 so energized and positioned with a sweep arm 327, 328 on a numbered contact, the stepper coil 324 is energized and closes switch 333 in lead 334 between the lines 300, 301 in which the coil 335 of CR-3 is disposed in series. Upon CR3 coil 335 being energized, the switch 311 in the upper conveyor 70 motor 60 circuit is closed and the motor 60 is energized and drives the upper conveyor 70. Switch 333 remains closed in all positions of the stepper 90 sections 325, 326 except the home position of stepper 90, section 325. Thus the motor 60 constantly drives the upper conveyor 70 until the stepper section 325 arm 327 comes to home contact H when all the bins 50 are loaded.

Upon CR3 coil 335 being energized it closes a switch 345 in lead 346 and lead 347 between the lines 300, 301 furnishing current to unit counter 288 clutch coil 348 and count coil 349 through normal open photo-cell operated switch 350. Each time a sheet interrupts the lamp beam to the photo-cell, the switch 350 changes position energizing the count coil 349 to move the unit counter 288 one increment.

When less than full bin capacity is used and the unit counter counts out with the stepper 90 arms 325, 326 in an intermediate location, the arms 325, 326 must be brought to their home position. Thus when unit counter 288 counts out it closes its own switch 350 in series with coil 351 of CR4 in lead 352 between the lines 300, 301. This in turn opens CR4 switch 353 in lead 323 which disconnects stepper coil 324 from the 24 V DC lines 320 and 321. It also closes switch 354 of CR4 in shunt lead 355 to lead 323 connecting lead 323 on one end to line 300 115 V AC. This in turn closes switch 358 in shunt lead 355 which connects at one end to lead 323 and the coil 324 of the stepper 90 through resistor 356 and rectifier 357. The other end of shunt lead 355 connects through lead 323 to 115 V AC line 301. This places half-wave rectified 115 V AC current

across the stepper coil 324 and makes it run free under the resultant 60 cycle voltage on the intermittent half-wave. When the stepper sweep arm 327 reaches the home position H on section 325, S-1 off-normal, switch 333 opens and this stops the stepper from further moving and it also drops out the coil 335 of CR3 relay; CR3 relay dropping out opens switch 311 in lead 310 and stops the upper conveyor motor 60. The motor 60 is stopped now and the stepper 90 has been returned to home in the operation of a single unit 40 or the last partially loaded unit of a bank.

However in the sheet loading operation, in the event of a unit lying in-line downstream, the switch 311A of the downstream unit in parallel with the switch 311 maintains the motor 60 running on the first unit to deliver sheets to the second unit and the sheets continue to flow through the first unit to the second unit.

To make the sweep arms 327, 328 of stepper 90 sections 325, 326 move incrementally from numbered contact to numbered contact sequentially and thus to open the sheet gates 67 successively in the upper conveyor 70 to load a sheet into each bin 50 sequentially, it is necessary to energize the stepper coil 324 (S-1) to cock the pawl and to then de-energize the stepper coil 324 to uncock the pawl which in uncocking advances the sweep arms 327, 328 one contact point. With the sweep arm 327 on the H contact the stepper coil 324 is not in an energizable circuit. To place the stepper coil 324 in an energizable circuit, the start switch 322 lies in the lead 323 to the stepper coil 324. Upon the start switch 322 being closed, it energizes the stepper coil 324 and the stepper pawl is cocked and uncocked moving the sweep arm 327 of section 325 from H contact to number 1 contact and the stepper coil is now in an energized circuit. Also gate solenoid coil 332 in lead 331 to the number 1 contact is energized and the first gate 67 at the upper conveyor 70 is open and ready to divert a sheet into the first bin 50. After the start switch 322 is closed and released, it opens; but the closing of the start switch and the movement of the stepper 90 arm 327 off H contact closes switch 333 by a cam which keeps switch 333 closed until the arm 327 again comes to the H contact.

This stepper pulse system also comprises a lead 336 between the lines 320, 321 which includes the coil 337 of CR1, a switch 338 of CR1, and a switch 339 actuated by the photo-electric cell 93. Lead 336 is connected by shunt lead 340 to lead 323 behind the start switch 322 connecting photo-cell action to the coil 324 (S-1) of stepper 90. A shunt lead 341 by-passes the switches 338 and 339 to lead 336 and to coil 337 of CR1. A switch 342 in shunt lead 341 is controlled by the stepper 90 sections 325, 326. When the sections 325, 326 are energized, the switch 342 is closed and pulls in the coil 337 of CR1. Upon coil 337 of CR1 being energized it opens switch 343 in gate sequence pulse lead 323.

When and while a sheet passes the photo-electric cell 93, it interrupts the beam and closes switch 339 operated by cell 93 closing a circuit through shunt 340 to lead 323 which energizes the coil 324 (S-1) of stepper 90. When the stepper 90 coil 324 is energized, it closes switch 342 (S-1 Int.) in shunt lead 341 to lead 336 to energize coil 337 of CR1. With coil 337 energized, switch 338 in lead 336 is closed locking in the

coil 337 of CR1 in lead 336 through switch 339 which is closed now as stated. With coil 337 energized, switch 343 (CR1) in lead 323 opens dropping out coil 324 of stepper 90 sections 325, 326. The prior energizing of the stepper coil 324 cocks the pawl; the now de-energizing of the stepper coil 324 allows the pawl to uncock to advance the sweep arms 327, 328 one position or increment (I.E.) to the next numbered contact. Upon the sheet completely passing by and clearing the beam to the cell 93, the cell operated switch 339 opens dropping out coil 337 of CR1 in lead 336. Also switch 338 opens and switch 343 closes when the coil 337 of CR1 drops out. The self lock-in of coil 337 through switch 338 obtains while the sheet is passing photoelectric cell 93 and switch 339 is closed. Thus after the sheet passes by the cell 93, the beam is not interrupted and switch 339 opens.

It will thus be understood that the stepper 90 receives a momentary pulse to cock the pawl when a sheet interrupts the beam in passing into a bin 50 as switch 339 is closed and switch 343 is closed but stepper coil 324 is quickly de-energized when its own energization closes switch 342 to the coil 337 of CR1, which when closed, energizes the coil 337 and this also opens switch 343 de-energizing the stepper coil 324. Thus the stepper 90 cocks and uncocks advancing the sweep arms 327, 328 to the next numbered contact to open the next sheet gate 67 at the top conveyor 70 to the next bin 50. As soon as the sheet at the prior gate 67 clears the beam of the photo-electric cell 93, the switch 339 opens interrupting the self-locked circuit of coil 337 of CR1 through switch 338. This readies all components for the next sheet to interrupt the beam of the cell 93 as it enters the next bin 50 and the described operation repeats when the next sheet is diverted by the now open next gate 67 to again interrupt the beam.

Should the paper jam in the beam while entering the pocket it continues to interrupt the beam and switch 339 remains closed holding in the coil 337 of CR1 holding switch 348 (CR1) open preventing re-energizing of stepper 90 coil 324.

BASIC UNIT CIRCUIT - SHEET JOGGING

Unit counter 288 counts out when a set of sheets (such as pages 1,2,3, etc.) have been delivered to all or the desired number of bins. Upon counting out, unit counter 288 closes switch 359 (ooc) in circuit 352 which energizes the coil 351 of CR4. CR4 then closes switch 408 in circuit 406 which energizes the coil 407 of CR9 and two phases are activated.

First: If less than all the bins have sheets, CR9 switch 402 closes in hold shunt circuit 405 to the coil 351 of CR4. This self-locks in CR4. CR4 closes switches 358 and 354 and opens switches 500 and 353 around the stepper coil 324. This removes the DC circuit from the stepper 90 and applies half wave rectified AC through switch 333, resistor 386, and half wave rectifier 357 causing the stepper 90 to run free at a 60 cycle stepping rate. When the stepper 90 circuit is energized the switch 333 is closed in circuit 334 energizing the coil 335 of CR3. When the stepper 90 reaches home position switch 333 of stepper 90 opens stopping the stepper at the home position H and de-energizing coil 335 of CR3. When CR3 is de-energized switch 345 opens and the unit counter 288 resets and this opens

switch 359 which de-activates circuit 352 to the coil 351 of CR4 but with hold shunt circuit 405 holding in CR4 in self locked-in condition. The first phase is quickly accomplished in a few seconds or less.

Second: The energizing of CR9 as previously stated also started the jogger motor M3-122 by closing switch 416 in jogger motor circuit 415. The action of jogging now starts and with rotation of gear 127, the dog 155 moves out of abutment with limit switch 126 whereupon limit switch 126 moves off contact A in shunt circuit 405 opening the circuit 405 to coil 351 and CR4 drops out and onto contact B in circuit 409-406 and thus closing hold shunt circuit 409 to circuit 406 to coil 407 of CR9.

Jogger motor 122 continues to rotate until dog 155 again comes into abutment with limit switch 126 and moves the switch 126 from contact B to contact A whereupon CR9 circuits 415, 409, and 406 are all open thus de-energizing CR9 and opening switch 416 in circuit 415 to the jogger motor 122 and the jogger motor 122 stops. As previously described the ratio between gear 127 and gear 129 driving the crank 123 is three-to-one so that in one rotation of gear 127, the crank 123 makes three oscillations to jog the sheets in the bins 50 three times.

After a page of each set of sheets is loaded into all or the selected number of bins 50, the counter 288 counts out to terminate loading and the jogger 56 is activated. After the desired number of sets of sheets have been loaded with a sheet of each set in each bin, the bins 50 are loaded as desired. Thus if 60 pages have been put in each bin 50 with each set jogged three times, it will be understood that the jogger 56 has jogged the sheets three times for each sheet or 180 times for the total sheets loaded in each bin. This insures that the sheets are in substantially accurate edge alignment for stapling at the end of loading the sheets in the bins 50.

The next operation is to stitch the pages or sheets together in each bin 50 in a book and to unload the stitched book from the bin to the lower conveyor and this is now described.

PRELIMINARY TO STAPLING AND UNLOADING

To set up the machine for stapling and unloading, the stapler and lower conveyor drive motor 61 is started. To start the motor 61, the operator presses the "forward" button which has two switches 420 and 445 in circuits 417 and 443 respectively. This actuates two circuits so that the motor 61 is driven and ready for the automatic self-cycling to staple the sheets into books, and to unload the books to the bottom conveyor as previously described and also as hereinafter set forth.

In the wiring diagram the closing of switch 445 in circuit 443 energizes the coil 448 of CR7 in circuit 447 through the normally closed centrifugal switch 444. When CR7 is energized it closes its own switch 419 in series with the forward button 420 and the normally closed basket switch 474 in circuit 417 and energizes the coil 418 of CR5. When CR5 is energized it closes its switches 438 and 442 and motor 61 (M2) starts. When the motor 61 (M2) gets up to speed centrifugal switch 444 opens in the motor 61 (M2) disconnecting the starting winding 440 and also de-energizing the coil 448 of CR7 which now is no longer needed as the sustaining relay CR5 coil 418 is energized through its

own switch 424 in circuit 431 around the start button switch 420. This provides a holding circuit maintaining the motor 61 (M2) running. The motor 61 (M2) thus drives the lower conveyor and also furnishes available running drive for operating the stapler drive transmission for driving the various drive shafts when their respective clutches are actuated.

STAPLING AND UNLOADING

The operator presses the stapler carriage "forward" travel button which has two switches: switch 470 in the stapling circuits and switch 475 in the jogger circuits 406, 409 and 412.

(JOGGER ABUTMENT)

Upon closing switch 475, the jogger 56 bumper bar 106 is advanced into abutting relationship against the sheets 200 in the bins 50. The purpose of advancing the bumper bar 106 into abutting contact with the sheets in the bins 50 in opposition to the stapler 159 is so that the sheets cannot move away from the stapler 159 when it enters each bin.

With switch 475 closed the coil 407 of CR9 is energized through switch 414 (JS-2) which is a normally closed limit switch at the full "in" projection of the jogger bumper bar 106. Upon CR9 being energized it closes switch 416 in series with the jog motor 122 (M3) and the jog motor moves the bumper bar 106 in advancing movement into the bins 50 against the sheets therein, and at its full "in" projection, the projection 155 on the hub of gear 127 engages limit switch 414 (JS-2) and opens it. When switch 414 opens, it de-energizes the coil 407 of CR9 and the switch 416 (CR9) opens in the jog motor 122 (M3) circuit 415 and the jog motor stops and this leaves the bumper bar 106 abutted against the sheets in the bins 50.

At the same time as the sheets in the bin are being stitched by the stapler, the turning of the stapler clinch drive shaft 136, FIG. 26, rotates the cam 136A against switch 411 (CS6) to close it (at the same time it closes switch 283) for a period of time in jogger circuits 410, 409, and 406 to coil 407 (CR9). When CR9 is energized it closes its switch 416 in circuit 415 energizing the jogger motor 122 (M3). This causes the jogger to first move projection 155 from limit switch 414 allowing limit switch 414 to close. Thus CR9 is self-held in through its own switch 413 (CR9) in series with switch 414 (JS-2). The jog motor 122 continues to run so as to again advance the projection 155 into contact with switch 414 (CS-6) to open it and de-energize the coil 407 of CR9 and de-energize jog motor 122 (M3) again leaving the bumper bar 106 abutting the sheets for the stapling operation in the next bin. This action of the bumper bar 106 occurs each time the sheets in a bin are stitched into a book and the book unloaded to the bottom conveyor preparatory to stitching the sheets in the next bin.

In the time the bumper bar is retracted from the sheets, the stapler carriage is moved to the next bin which trips the trap door on the last bin unloading the last stitched book to the bottom conveyor without interference from the bumper bar 106. This obtains because at the time the book is unloaded the bumper bar is retracted.

BASIS FOR AUTOMATIC CYCLING

The depressing of the forward button also closes manual switch 470 to start the automatic cycling. As previously explained, an electrically actuated clutch 137 is on each drive shaft 134, 135, and 136 and that each clutch 137 is mechanically de-activated by a pin 142 upon the desired degrees of rotation. The switch 470 is also used to re-start automatic cycling after interruption by a stapler jam.

10 A clutch coil 461 (S-2) activates the clutch 137 on cross-slide drive shaft 135. The clutch coil 461 (S-2) is energized to clutch drive to the cross-slide shaft 135 by the closing of any one of three switches: the manual switch 470 to advance (or retract) the cross-slide 160 to start (or re-start) cycling; the switch 282 to advance the cross-slide 160 during auto-cycling; and the switch 283 to retract the cross-slide 160 during auto-cycling.

15 It will be remembered that the cross-slide drive shaft 135 in one sequence rotates 180° to advance the cross-slide 160 and in the next sequence rotates 180° to retract the cross-slide 160. Both advancing and retracting motion of the cross-slide 160 occurs via the crank 164 and crank pin 165 in cam-slot 166, FIG. 18, Sheet 14, with rotation of the cross-slide drive shaft 135. It will thus be understood that the manual switch 470 advances or retracts the cross-slide 160 depending on which is its next sequence in automatic cycling by rotation of cross-slide drive shaft 135 by 180°.

20 30 A clutch coil 472 (S-3) activates the clutch 137 on the stapler clinch drive shaft 136. The clutch coil 472 (S-3) is energized by the closing of switch 280 to clutch drive to the stapler clinch drive shaft 136 to actuate the stapler to clinch during auto-cycling.

25 35 A clutch coil 459 (S-1) activates the clutch 137 on the carriage drive shaft 134. The clutch coil 459 (S-1) is energized by the closing of the switch 281 to clutch drive to the carriage drive shaft 134 to advance the carriage during auto-cycling to the next bin.

40 45 With the carriage 146 at its home position and with the stapler 159 ready to advance into the adjacent bin 50, (slightly moved from the position of FIG. 2, Sheet 4 to the last bin 50) and with the desired sheets in the bins 50, the machine is ready for stapling and unloading automatic cycling.

AUTOMATIC CYCLING

Upon the manual closing of switch 470 the coil 461 (S-2) (140-A) is energized and the clutch 137 on the cross-slide drive shaft 135 connects drive and the cross-slide 160 advances the stapler 159 into the adjacent bin 50 whereupon the clutch 137 after 180° rotation is de-activated by its pin 142A. Upon turning 180° the cam 135C on the cross-slide drive shaft 135 closes switch 280 to the coil 472, S-3, FIG. 40, Sheet 2, and FIG. 26, Sheet 18.

50 55 Upon the automatic closing of switch 280 the coil 472 (S-3) (140A) is energized and clutch 137 on the stapler clinch drive shaft 136 connects drive and the stapler 159 is actuated to clinch a staple in the sheets in the bin to stitch them together in a book and to release the stapler 159. This occurs in 360° rotation of the stapler-clinch drive shaft 136 whereupon the clutch 137 is de-activated by contact with its pin 142A. Upon turning 360° the cam 136C on the stapler clinch drive shaft 136 closes switch 283 to the coil 461, S-2.

Upon the automatic closing of the switch 283 the coil 461 (S-2) (140A) is energized and the clutch 137 on the cross-slide drive shaft 135 connects drive and the cross-slide 160 retracts the stapler 159 from the bin 50. This occurs in 180° rotation whereupon the clutch 137 is de-activated by its pin 142A. Upon turning 180° the cam 135C on the cross-slide drive shaft 135 closes switch 281 to the coil 459, S-1, (and also closes switch 411 to advance the bumper bar as previously stated).

Upon the automatic closing of the switch 281 the coil 459, S-1, (140A) is energized and the clutch 137 on the carriage drive shaft 134 connects drive and the carriage drive shaft 134 advances the carriage 146 to the next bin. This occurs in 180° rotation whereupon the clutch 137 is de-activated by its pin 142A. Upon turning 180° one of the two lobes on the cam 134C on the carriage drive shaft 134 closes switch 282 to the coil 461, S-2.

The closing of switch 282 in automatic cycling substitutes for the manual switch 470.

Upon the closing of switch 282, the coil 461 (S-2), (140A), is energized and the clutch 137 on the cross-slide drive shaft 135 connects drive and the cross-slide 160 advances the stapler 159 into the adjacent bin. This occurs in 180° rotation whereupon the clutch 137 is de-activated by its pin 142A. Upon 180° rotation of the cross-slide drive shaft 135, the cam 135C on the cross-slide drive shaft 135 closes switch 280 to the coil 472, S-3. The next sequence now automatically occurs as previously described.

Thus the stapler is (A) advanced into a bin, (B) clinched to stitch, (C) retracted, and (D) the carriage advanced to the next bin automatically in self-repeating automatic cycles with the completion of A initiating B, the completion of B initiating C, the completion of C initiating D, and the completion of D initiating A.

INTERRUPTION BY STAPLER JAM A

When the stapler condition sensor mechanism determines that the stapler 159 is in proper operating condition, the sensor shaft 211, FIG. 26, Sheet 18, is angularly located to position the cam 223 to close the switch 224 in series with switch 283 in circuit 465. Under this condition when switch 283 closes, the coil 461, S-2, is energized and the cross-slide is retracted as previously stated.

However, when the sensor mechanism determines that the stapler 159 is not in proper operating condition, it prevents the sensor shaft 211 from positioning the cam 223 to close the switch 224 in series with switch 283 in circuit 465.

Under this condition when switch 283 closes, the coil 461 is not energized because switch 224 is open in the circuit 465 and the automatic cycling is interrupted with the cross-slide and stapler advanced into the adjacent bin. The operator upon seeing that the automatic cycling has stopped, inspects the stapler 159 and puts it in proper operating condition. The operator then pushes the reset button closing switch 470 in shunt circuit 469 direct to the coil 461, S-2, and the cross-slide is withdrawn and the automatic cycling is thus restarted and then continues.

UN-USED BIN BY-PASS

This action is provided by a forward traverse circuit having a traverse switch including three sections 451,

463, and circuit selector section 457. The selector section 457 is normally closed in circuit 456 to the coil 459 of S-1, (140A). Upon the traverse switch being activated selector section 457 opens circuit 456 and changes the coil 459 of S-1, (140A), to circuit 452 and section 463 opens the circuits to coil 461 S-2 and coil 472 S-3. Section 451 removes the holding circuit from relay CR-5, 418. This keeps the clutch 137 transferring drive to shaft 134A until the forward button is released and the selector switch de-activates. This gives the forward button switch 445 solitary control over coil 459 S-1, (140A), through circuit 452 so that upon depressing the forward button the carriage traverses with coil 459 energized connecting drive to the carriage drive shaft 134. When the carriage 146 traverses to the desired bin, the operator releases the forward button and the carriage stops. By now de-activating the traverse switch and then depressing the start button, switch 470 and switch 475 close and automatic cycling is started and automatically continues.

A limit switch 446 in series with the forward drive circuit 499 and a limit switch 421 in forward drive circuit 417 are operated by contact with the carriage 146 to disconnect forward drive at its forward limit of travel from the home position. A limit switch 454 in series with the reverse drive circuit 455 and a limit switch 430 from circuit 425 are operated by contact with the carriage 146 to disconnect reverse drive at its reverse limit of travel to the home position. A stop switch 422 interrupts circuit 417 to the coil 418 of CR5 which opens switch 464 in circuit 456 to stop automatic cycling and carriage traversing and is provided for use of the operator to shut down unloading for any reason.

CARRIAGE REVERSE TRAVERSE

To return the carriage 146 to its home position after stapling and bin unloading is completed, the operator activates the traverse switch with previously described result and also depresses the reverse button which has two switches 429 and 453. Closing of switch 429 in circuit 426 energizes the coil 427 of CR6 whereupon CR6 closes switch 432 CR6 in shunt circuit 431 and self-locks in the coil 427 as switch 428 CR7 and reverse limit switch are closed. With the energizing of CR6 switch 434 CR6 in circuit 433 and switch 436 CR6 in lead 435 are closed applying reversely polarized current to the starting winding 439 of motor 61 M2 and the motor starts to rotate in reverse which drives the carriage drive shaft 134 in reverse for moving the carriage 146 in reverse to the home position as previously stated.

Closing of switch 453 in circuits 455, 483 and 443 energizes the field coil 440 of motor 61 M2 as reverse limit switch 454 is closed. This also energizes the coil 448 CR7 in circuit 447 which closes switch 428 CR7 in circuit 426 as previously stated.

When the carriage 146 arrives at the home position it opens reverse limit switch 454 and the carriage stops at the last bin ready for use in the next stapling and bin unloading operation.

MULTIPLE UNIT WIRING

The lines 300A and 301A at the top of FIG. 40, Sheet 21, lead to other basic units 40 which may be in end-to-end and/or superposed relationship to the first

unit 40. In this connection it will be understood that the top and bottom conveyors of the in-line units are kept running to provide inter-delivery.

In the case of superposed units, the bottom conveyor of the upper unit may be deleted and the top conveyor of the lower unit used in unloading books from the upper unit. In this instance during the time the upper unit is being unloaded, the top conveyor of the lower unit is driven in reverse so that it will convey the 5 stitched books to the book delivery end. To effect this the coil 490 of CR8 in circuit 466 is energized and the switches 491 and 492 are opened in circuit 310 at top conveyor motor 60 and the switches 493 and 494 closed reversing the polarity to the motor 60 which 10 now runs in reverse as power is connected in circuit 310 by switch 495, CR8.

The novel features of the collator and the various systems are defined singly and in combination in the appended claims.

We claim:

1. A collating machine and stapler combination comprising of a sheet collating machine including a frame having opposite ends and opposite sides;

a top conveyor mounted on said opposite sides for moving sheets horizontally from one said end toward the other said end;

gates mounted between said opposite sides below said top conveyor for diverting sheets downwardly 30 from said top conveyor; said gates being operable between a sheet diverting position and a normal sheet by-passing position;

a plurality of relatively vertical spaced plates mounted between said sides below said gates defining bins therebetween;

one said bin being associated with and below each said gate and having an open top for receiving sheets diverted by said associated gate;

a bottom closure on each said bin constituting the 40 bottom of each said bin for retaining the sheets in each said bin during collating;

means for selectively operating said gates between said diverting and by-passing positions at each said bin to divert sheets from said top conveyor to each said bin and to by-pass sheets traveling thereon to gates downstream;

each said bin having an open end portion for exposing 45 at least a portion of the edges of the sheets in each said bin;

said bin plates having a cut away portion in the area of said open end portion for exposing the surface of the sheets adjacent the exposed edges of the sheets;

said bins open end portions and said bin plates cut-away portions thus providing for positioning a 50 stapler over the surfaces of the sheets to drive a staple through the sheets to stitch the sheets together while in said bins;

a motor,

brackets mounted on one said side of said frame at the ends thereof,

rails extending between said brackets,

a carriage mounted on said rails for traveling 55 between said ends of said frame,

a cross-slide mounted on said carriage,

at least one stapler mounted on said cross-slide; said cross-slide on said carriage having reciprocating motion for extending said stapler into said bins to stitch the sheets together and for retracting said stapler from said bins after the stitching operation; a carriage drive shaft lying between said brackets for moving said carriage on said rails,

drive means connected between said carriage drive shaft and said carriage for moving said carriage linearly on said rails,

a normally disconnected clutch between said motor and said carriage drive shaft and drive means for connecting and disconnecting rotational drive to said carriage drive shaft and to said drive means,

control means for activating and de-activating said clutch to move said carriage incrementally from bin to bin and to stop said carriage at each said bin during the stapling operation;

a cross slide drive shaft lying between said brackets for extending and retracting said cross-slide and said stapler relative to said bins,

cross-slide drive means connected between said cross-slide drive shaft and said cross-slide for reciprocating said cross-slide relative to said carriage,

a normally disconnected clutch between said motor and said cross-slide drive shaft and said drive means for connecting and disconnecting rotational drive to said cross-slide drive shaft and to said cross-slide drive means to move said cross-slide and stapler into position at said bins to stitch the accumulated papers in said bins;

control means for activating said clutch to extend said cross-slide and to retract said cross-slide relative to said bins selectively;

a stapler on said cross-slide,

a stapler drive shaft lying between said brackets for operating said stapler,

stapler drive means connected between said stapler drive shaft and said stapler for actuating said stapler when in driven connection to said stapler drive shaft,

a normally disconnected clutch between said motor and said stapler drive shaft and drive means for connecting and disconnecting rotational drive to said stapler drive shaft and to said stapler drive means, and

control means for activating said clutch to operate said stapler to stitch the accumulated papers together in said bins;

all said control means being operationally integrated to automatically move said carriage incrementally from bin to bin and dwell, to extend said cross-slide, to actuate said stapler, to retract said cross-slide, and to repeat relative to said next bin.

2. In a machine as set forth in claim 1, said control means for said stapling mechanism comprising,

a control circuit, switches in said control circuit with one said switch radially adjacent said carriage drive shaft, one said switch radially adjacent said stapler drive shaft, and two said switches radially adjacent said cross-slide drive shaft;

cams on said shafts for operating said switches to close momentarily in conjunction with shaft rotational position at an angular location;

a clutch on each said drive shaft for selectively rotat-
ing each said shaft;
said shafts being normally stationary and said
clutches normally rotating;
said clutches having drive means and electrically 5
energizable drive connecting means in said control
circuit activated by said switches closing momen-
tarily;
said clutches self-maintaining clutch drive connec-
tion once drive is established; 10
said clutch drive means being mechanically discon-
nectable;
dogs located radially adjacent each said clutch at a
circumferential point for contacting and discon- 15
necting said clutches when said shafts are at a
desired angular position;
the sequence of the operation cycle of said stapling
mechanism being;
A. indexing the carriage to a bin by rotation of said 20
carriage drive shaft,
B. advancing the cross-slide toward the bin by rota-
tion of said cross-slide drive shaft,
C. operating the stapler to stitch the papers by rota-
tion of said stapler drive shaft, 25
D. withdrawing the cross-slide from the bin by rota-
tion of said cross-slide drive shaft,
a start switch in said control circuit,
said cycle being automatically repeated upon said
start switch being closed as follows: 30
a. said carriage drive shaft rotates to engage its
said clutch with its said dog to disconnect drive
to said carriage drive shaft after the carriage is
indexed to the next bin also advancing said cam
on said carriage drive shaft to close said ad- 35
jacent switch to energize clutch drive to said
cross-slide drive shaft to advance said cross-slide
into said bin;
b. said cross-slide shaft then rotates to engage its 40
said clutch with its said dog to disconnect drive
to said cross-slide shaft after the cross-slide is
advanced into said bin also advancing said cam
on said cross-slide shaft to close said adjacent
switch to energize clutch drive to said stapler 45
drive shaft to operate said stapler to stitch the
accumulated sheets in said bin;
c. said stapler drive shaft then rotates to engage its
said clutch with its said dog to disconnect drive
to said stapler drive shaft after the accumulated 50
sheets are stitched together in said bin also ad-
vancing said cam on said stapler drive shaft to
close said adjacent switch to connect clutch
drive to said cross-slide drive shaft to retract
said cross-slide from said bin. 55
d. said cross-slide drive shaft then rotates to en-
gage its said clutch with its said dog to discon-
nect drive to said cross-slide drive shaft after
said cross-slide is withdrawn from said bin also 60
advancing said cam on said cross-slide drive
shaft to close said adjacent switch to energize
clutch drive to said carriage drive shaft to index
said carriage to the next said bin.
said cycle thereby being self-repeating. 65
3. In a machine as set forth in claim 1, a sensor
device for reading a stapler operating condition for
determining if (said stapler head and anvil are jammed

together, if the striker is jammed in the stapler head, or
if) the stapler is in proper operating condition comprising,
a check switch disposed in said control circuit in se-
ries with said switch operated by said cam on said
stapler drive shaft to interrupt said circuit to said
clutch on said cross-slide drive shaft if said stapler
is jammed or to close the circuit if said stapler is in
proper operating condition.
a sensor stub shaft,
a feeler lever on said stub shaft,
a finger on said feeler lever having a high surface
equating to the stapler anvil and head jammed
condition of said stapler and a low surface equat-
ing to proper operating condition of said stapler;
said feeler lever when not in alignment with and
moving under said stapler head equating to striker-
head jammed-in condition of said stapler;
said finger and feeler lever angularly locating said
stub shaft dependent on said stapler condition;
a transfer lever on said stub shaft,
a push-pull rod connected to said transfer lever,
a rocker guard operated by said push-pull rod;
said rocker guard having a center notch equating to
proper stapler condition and a raised surface on
either side of said notch equating to said inopera-
tive stapler conditions;
a sensor shaft, a radial arm on said sensor shaft, a link
connecting said radial arm to said push-pull lever,
and a spring lying between said link and said push-
pull rod to allow sensor shaft angular movement
variance relative to stapler condition,
a radial tab fixed on said sensor shaft at the center
position of said rocker guard and notch so as to
enter said notch when said rocker guard is at
center permitting the sensor shaft to make its full
angular motion and to encounter the raised sur-
faces on said rocker guard when said rocker guard
is on either side of center position to prevent said
sensor shaft making its full angular motion;
said sensor shaft having a check cam which closes
said check switch when said sensor shaft has made
its full angular motion,
a sensor actuator cam on said stapler drive shaft,
a sensor actuator lever on said sensor shaft riding
against said sensor cam to impart rocking motion
to said sensor shaft in conjunction with said sensor
cam rotation;
spring biased linkage in said sensor lever allowing
varying sensor shaft angular motion relative to said
sensor cam movement;
said sensor shaft via said spring linkage of said sensor
lever and said spring between said push-pull lever
and said link being capable of taking an angular
position as located by said notch and said raised
surfaces of said rocker guard in abutment with said
radial tab on said sensor shaft such as home position
of full angular motion in said notch and dis-
placed position on said surfaces of less than full an-
gular motion; and
a check switch cam on said sensor shaft closing said
check switch to complete said circuit when said
sensor shaft makes its full angular motion with said
radial tab lying in said notch of said rocker guard;

said check switch cam on said sensor shaft not closing said check switch with said sensor shaft making less than full angular motion thereby preventing closing of the circuit to initiate the next sequence in the cycle thereby interrupting automatic cycling because the stapler is not in an operative condition to stitch the accumulated papers in said bins.

4. A collating machine and stapler combination comprising relatively vertical collating machine plates defining bins, a closure at the bottom of each said bin, means for loading sheets into the top of each said bin; said plates having a relief for exposing at least a portion of the edge and surface of sheets in said bins for a stapler to enter over the sheets to stitch the sheets together in a book while the sheets are in said bins, comprising:

a carriage,

means movably supporting said carriage for travel from bin to bin,
actuating means for moving said carriage from one 20
said bin to the next,
a cross-slide on said carriage,
a stapler on said cross-slide,
actuating means on said carriage for advancing said
cross-slide and stapler to the sheets in said bins and
retracting said cross-slide, and
actuating means on said carriage and cross-slide for
operating said stapler to stitch the sheets in a bin
together in a book.

5. In a combination as set forth in claim 4, a removable closure at the bottom of each said bin;
said closure at each said bin bottom being a spring 30
pressed trap door,
an arm on each said door for opening each said door, 35
and

a dog on said carriage adapted to contact said arm
and open said door when said carriage moves from
said bin having a stitched book to unload the book
from said bin.

6. In a combination as set forth in claim 5, a bottom 40
conveyor below said bins; said bottom conveyor receiving the stitched books from said bins when they are unloaded and transporting the books to a point outwardly of said bins.

7. In a combination as set forth in claim 4,
a transmission on said machine having selectively 45
operable drive means separately connected to
each said carriage actuating means, said cross-
slide actuating means, and said stapler actuating
means;

and control means for sequentially selectively operating said drive means in repeating cycles to 50
advance said cross-slide and stapler,
to actuate said stapler, to retract said cross-slide and
stapler, and to move said carriage to the next bin.

8. In a combination as set forth in claim 4,
each said plate having a transverse slot;
a jogger mechanism at one side of said plates having 55
a bumper bar reciprocally disposed in the slots of
said plates transversely of said bins,
a stop bar on the other side of said plates opposite to
said jogger mechanism and said bumper bar,
said jogger mechanism intermittantly advancing said

bumper bar into contact with sheets in said bins to jog the sheets against said stop bar to thereby align the sheets edgewise in said bins.

9. In a combination as set forth in claim 8,
said jogger mechanism being adapted to advance and
hold said bumper bar against the sheets in said bins
in opposition to said stapler when said stapler is
advanced into said bins to prevent said stapler dis-
placing sheets in its advancing movement.

10. A collating machine combination comprising substantially vertical plates defining bins, a closure at the bottom of each said bin,

means for loading sheets into the top of each said
bin;
each said plate having a relief for exposing a portion
of the edge and face surface of sheets in said bins
for a stapler to enter over the sheets to stitch the
sheets together in a book while in said bins;

a carriage,

means movably supporting said carriage for travel
from bin to bin,

actuating means for moving said carriage from one
said bin to the next,

a cross-slide on said carriage,
a stapler on said cross-slide,
actuating means on said carriage for advancing said
cross-slide and stapler to the sheets in said bins and
retracting said cross-slide,

actuating means on said carriage and cross-slide for
operating said stapler to stitch the sheets in a bin
together in a book;

said closure at each said bin bottom being a spring
pressed trap door,

an arm on each said door for opening each said door,
a dog on said carriage adapted to contact said arm
and open said door when said carriage moves from
said bin having a stitched book to unload the book
from said bin;

a transmission on said machine having selectively
operable drive means separately connected to
each said carriage actuating means, said cross-
slide actuating means, and said stapler actuating
means;

control means for sequentially selectively operating
said drive means in repeating cycles to advance
said cross-slide and stapler, to actuate said stapler,
to retract said cross-slide and stapler, and to move
said carriage to the next bin;

each said plate having a transverse slot;

a jogger mechanism at one side of said plates having
a bumper bar reciprocally disposed in the slots of
said plates transversely of said bins, and

a stop bar on the other side of said plates opposite to
said jogger mechanism and said bumper bar,
said jogger mechanism intermittantly advancing said
bumper bar into contact with sheets in said bins to
jog the sheets against said stop bar to thereby align
the sheets edgewise in said bins;

said jogger mechanism being adapted to advance and
hold said bumper bar against the sheets in said bins
in opposition to said stapler when said stapler is
advanced into said bins to prevent said stapler dis-
placing sheets in its advancing movement.
